UNITED STATES PATENT OFFICE

2,186,228

SEWING MACHINE

Samuel W. Avis, Providence, R. I., assignor to
 The Reece Button Hole Machine Company,
 Boston, Mass., a corporation of Maine

Application January 27, 1938, Serial No. 187,175

62 Claims. (Cl. 112—70)

This invention relates generally to sewing machines and more particularly to sewing machines of that type which are used for making a "tack" at the end of a button hole slit or a pocket slit in garments or any other places where a reinforcing tack is desirable.

It is among the objects of the present invention to provide a sewing machine which is capable of forming a tack of variable dimensions within limits defined only by the limits of adjustment of certain elements of the machine. More particularly, the machine shall be so universally adjustable as to vary the overall length of the tack, and/or its number of underlying 10 stitches, and/or its number of overlying stitches and/or the width of the overlying stitches.

It is another object of the present invention to provide a sewing machine of the above type in which the material remains stationary and the sewing elements of the machine are moved relative to the material for the formation of a tack.

It is another object of the present invention to provide novel structure in a sewing machine of the above type for automatically severing both the needle thread and the bobbin thread from their supplies at the end of a tacking operation, leaving thereby a sufficient length of upper thread in the needle to complete a lock stitch on the first 25 reciprocation of the needle during the following tacking operation.

It is also among the objects of the present invention automatically to clamp the severed or leading end of the bobbin supply thread to the 30 throat plate of the machine, so that the bobbin thread may immediately form a lock stitch together with the loop of upper thread which is cast by the needle on its first reciprocation during the next tacking operation.

Before explaining in detail the present invention it is to be understood that the invention is not limited in its application to the details of construction and arrangement of parts illustrated in the accompanying drawings, since the 40 invention is capable of other embodiments and of being practiced or carried out in various ways. Also it is to be understood that the phraseology or terminology employed herein is for the purpose of description and not of limitation, and it 45 is not intended to limit the invention claimed herein beyond the requirements of the prior art.

In the drawings:

Fig. 1 illustrates an example of a tack made by a machine which embodies the present invention.

Fig. 2 is a vertical section through the machine which embodies the present invention. More particularly this section is taken on the line 2—2 of Fig. 4.

Fig. 3 is another vertical section through the machine, taken substantially on the line 3—3 of Fig. 4.

Fig. 4 is a horizontal section through the machine, taken substantially on the line 4—4 of Fig. 3.

Fig. 5 is a fragmentary section through one of the clutches of the machine, taken substantially on the line 5—5 of Figs. 4 and 6.

Fig. 6 is a fragmentary section through the same clutch taken substantially on the line 6—6 of Fig. 5.

Fig. 7 is a fragmentary section similar to Fig. 5, showing certain elements of the clutch in different positions of cooperation, however.

Fig. 8 is a horizontal section through the machine, taken substantially on the line 8—8 of Figs. 2 and 3.

Figs. 9 and 10 are fragmentary sections, taken on the lines 9—9 and 10—10, respectively, of Fig. 8.

Fig. 11 is an enlarged fragmentary section, taken substantially on the line 11—11 of Fig. 3.

Fig. 12 is an enlarged fragmentary section, taken on the line 12—12 of Fig. 3.

Figs. 13 to 15, inclusive, are fragmentary sections taken substantially on the lines 13—13, 14—14 and 15—15, respectively, of Fig. 3.

Fig. 16 is an enlarged fragmentary section through certain cooperating elements of the machine.

Fig. 17 is a diagrammatic view, illustrating one of two identical intermittent rises in each convolution of the continuous groove of a screw-type feed cam of the machine.

Fig. 18 is an enlarged section, taken substantially on the line 18—18 of Fig. 16 and showing a follower in cooperation with the rise illustrated in Fig. 17.

Fig. 19 is a diagrammatic view, illustrating one of two identical intermittent rises in each convolution of the continuous groove of another screw-type feed cam of the machine.

Fig. 20 is an enlarged section through a follower which cooperates with the cam element shown in Fig. 19.

Fig. 21 is an enlarged, fragmentary section, taken on the line 21—21 of Fig. 3.

Fig. 22 diagrammatically illustrates the invariable coordination existing between certain

elements of the machine which operate in timed relation and one of which is adjustable.

Fig. 23 is a fragmentary plan view of a small portion of the machine, particularly that portion thereof which is encircled by the dot-and-dash line 23 in Fig. 4.

Fig. 24 is a front elevation of the structure shown in Fig. 23.

Fig. 25 is a drawn-out perspective view of the 10 main cam shaft of the machine as viewed in the direction of the arrow 25 in Fig. 4.

Figs. 26 and 26a show certain detail structure of the machine which cooperates to index the cam shaft in Fig. 25 at the proper times in the 15 cycle of operation of the machine.

Figs. 27 to 30, inclusive, are detail views of certain cams mounted on the main cam shaft.

Fig. 31 is a greatly enlarged, fragmentary section, taken substantially on the line 31—31 of 20 Fig. 2.

Fig. 32 perspectives illustrates the shortly occurring severance of the upper and lower threads from their supplies and the anchorage of the leading or severed end of the upper and lower 25 thread supply to the throat plate of the machine.

Fig. 33 is a greatly enlarged, fragmentary section, taken substantially on the line 33—33 of Figs. 2 and 31.

Fig. 34 is a fragmentary section similar to Fig. 30 33, showing the elements in different positions of cooperation, however.

Fig. 35 is a fragmentary section, taken on the line 35—35 of Fig. 33.

Fig. 36 is a fragmentary section, taken substantially on the line 36—36 of Fig. 3.

Fig. 37 is an enlarged fragmentary section through a certain clutch of the machine.

Figs. 38 to 46, inclusive, diagrammatically illustrate certain coordinated positions between the 40 needle crank and two feed cams of the machine.

Fig. 47 is a chart which graphically illustrates the timed relation of certain major operations performed by the machine during one cycle of operation of the same.

Referring to the drawings, the machine therein illustrated forms a tack of variable dimensions within limits defined only by the limits of adjustment of certain elements of the machine. An 50 example of a tack produced by the present machine is illustrated in Fig. 1, and consists of four superimposed lines or rows of underlying stitches *a* and a row of overlying or cover stitches *b*. The underlying as well as overlying stitches are all lock stitches as evidenced by the showing of a 55 shuttle in the drawings, but chain stitches could be used in the formation of the tack if desired, as will be more fully explained hereinafter.

The supporting structure of the present machine comprises three frames 50, 51 and 52 (Fig. 3) which are mounted together in any suitable manner and support the various operating devices of the machine. More particularly, the base frame 50 supports the other frames 51 and 52 which will be hereafter referred to as the "horn" and "head", respectively, of the machine. The various operating devices of the machine, which are supported by the frames 50, 51 and 52, may be termed as follows: the needle reciprocating device A (Fig. 2), the rotary drive B for the thread handling element (Fig. 3), the feeding device C for the needle and thread handling element longitudinally of the tack (Fig. 3), the needle vibrating device D (Fig. 3), the thread severing and clamping device E (Figs. 33 to 35,

inclusive), and the control F for the proper operation of the preceding devices (Fig. 25).

Needle reciprocating device A

As best shown in Fig. 2, the needle 53 is carried by a needle bar 54 which is axially reciprocable in bosses 55 of a yoke 56 that is provided with a hollow shank 57. The shank 57 is rotatably mounted in an outer sleeve 58 which is in turn 10 axially slidable in a boss 59 of the head 52 of the machine. Any suitable means, such as a pin and slot between the boss 59 and the sleeve 58 (not shown), may be used in order to prevent rotation of said sleeve, yet permit axial movement 15 of the same in the boss 59. A collar 60, suitably secured to the shank 57 of the yoke 56 and engaging the adjacent end of the sleeve 58, retains the opposite end of the latter in permanent engagement with an annular shoulder 61 of the yoke 20 56, wherefore said yoke 56 is axially movable together with the sleeve 58. Rotatable in the hollow shank 57 of the yoke 56 and a coaxially aligned sleeve 62 is the needle-crank shaft 63, a reduced end 64 of which extends beyond the yoke 25 56 and the opposite end of which is provided with a hand wheel 65 on the outside of the head 52. Mounted on the reduced shaft portion 64 is a crank disc 66 which has the usual pitman connection 67 with the needle bar 54 in order to 30 reciprocate the latter. Journalled on the reduced shaft portion 64, and interposed between the crank disc 66 and the yoke 56, is a member 68, the function of which will be described hereinafter. The annular shoulder 70 of the needle crank 35 shaft 63 is held in permanent engagement with an annular shoulder 72 of the yoke by the crank disc 66 and the member 68, wherefore the needle shaft 63 is axially movable in either direction together with the yoke 56 and the sleeve 58, as a 40 unit.

While the needle shaft 63 may be manually rotated at any time by the hand wheel 65, the same is ordinarily power-driven and connected with any suitable prime mover by means of a 45 clutch 74. The clutch 74 is in reality a double clutch, to wit, a "main" clutch and a "sewing" clutch. The prime mover may be an electric motor (not shown) which is connected by a belt 76 (Fig. 4) with a pulley 78 that is either drivingly connected, or integral, with another pulley 80. The pulleys 78 and 80 are rotatably mounted in any suitable manner on the outside of the base frame 50, and the pulley 80 drives another pulley 82 by means of a belt 84. The pulley 82 55 is mounted on the earlier mentioned sleeve 62 (Fig. 2) through which the needle shaft 63 extends. Keyed or otherwise secured to the sleeve 62 as at 86 (Fig. 5) is the common driver 88 of the double clutch 74. The sleeve 62 itself is journalled in a bearing bracket 90 which is suitably mounted at 92 on the head 52 (Fig. 2). The common driver 88 of the double clutch 74 is a disc, provided with annular recesses 94 in its opposite faces in which are located portions of 60 the two driven members 96 and 98 of the main clutch and sewing clutch, respectively. More particularly, the driven member 96 of the main clutch is freely rotatable on the sleeve 62, while the driven member 98 of the sewing clutch is 65 mounted on the needle-crankshaft 63 and provided with a tubular extension 100 which projects into the hollow shank 57 of the yoke 56 and is internally splined at 101 to the needle shaft 63. The common driving member 88 as 70 76 75

well as the driven members 96 and 98 of the clutch 14 are held axially immovable.

Inasmuch as the main clutch and the sewing clutch are of the same construction and operation, only the latter clutch will be described in detail. As best shown in Figs. 5 and 6, the driven member 98 of the sewing clutch is in the form of a disc which has a laterally extending lug 102, providing a socket 104 for the roller-shaped portion 106 of a dog 108 which is normally urged into engagement with an inclined shoulder 110 in the rim 112 of the driving member 88 by means of a spring 114, anchored at 116 in the driven member 98 and received in grooves 118 and 120 of said driven member and the dog 108, respectively. The driving member 88 normally rotates in a clockwise direction as viewed in Fig. 5, so that its rotary motion is transmitted to the driven member 98 through the inclined shoulder 110 and the dog 108. The driven member 98 is disengaged from the driving member 88 by a shifter 122 which is journaled on a horizontal shaft 126 (Fig. 4), suitably supported in a bracket 128 and a boss 130 of the head 52. The shifter 122 is centrally recessed at 132 (Fig. 6) to receive a plunger 134. A pin 136 is secured to the plunger 134 and extends with its two opposite ends into two diametrically opposite slots 138 in the shifter 122. A spring 140 is located in the recess 132 and normally urges the plunger 134 to the right as viewed in Figs. 5 and 6, i. e., into a position in which the pin 136 engages the right end walls of the slots 138 as viewed in Fig. 6. While the clutch members 98 and 88 are engaged, the shifter 122 is out of the path of rotation of the dog 108, a portion of which projects beyond the rim 112 of the driving member 88. On rocking the shifter 122 into the position shown in Fig. 5, the plunger 134 is brought into the path of rotation of the dog 108 and rocks the same counter-clockwise as viewed in Fig. 5 into the position shown in Fig. 7 in which the dog engages a machined surface 142 of the driven member 98 and clears the inclined shoulder 110 of the driving member 88, thus causing clutch disengagement. The spring 140 will momentarily yield and considerably cushion the impact between the plunger 134 and the dog 108 when the clutch 88, 98 is disengaged. In order to prevent the driven member 98 from backing-up even slightly in its disengaged position and thereby perhaps occasion an unauthorized reengagement of the clutch, a latch 144 is pivotally mounted on the shifter 122 and continuously urged against a stop pin 146 by a spring 148. While the plunger 134 knocks the dog 108 from driving engagement with the inclined shoulder 110, an inclined surface 150 of a pin 152 in the driven member 98 cooperates with an inclined surface 154 of the latch 144 in the manner shown in Fig. 5, thereby rocking said latch out of the path of rotation of said pin until the latter clears the former, whereupon the latch snaps into engagement with a machined flat 156 of said pin 152, i. e., just when the dog 108 has been forced into engagement with the surface 142 of the driven member 98 (Fig. 7). Hence, the driven member 98 is arrested against rotation in any direction immediately upon clutch disengagement. To reengage the driven member 98 with the driving member 88, the shifter 122 is rocked in the opposite direction so as to withdraw the plunger 134 from engagement with the dog 108, whereupon the spring 144 forces said dog into reengagement with the inclined shoul-

der 110 of the driving member 88. On rocking the shifter 122 into clutch-engaging position, the latch 144 is also immediately withdrawn from the pin 152 due to the engagement of the former with the stop pin 146 on the shifter 122.

The sewing clutch 88, 96 is engaged and disengaged by a shifter 158 (Fig. 4) which is of the same construction, and performs in the same manner, as the shifter 122. The shifter 158 is also freely rotatable on the shaft 126.

Rotary drive B for the thread handling element

The thread handling element in the horn 51 of the machine is shown in form of a shuttle 160 (Fig. 2) which is mounted on a combined support and drive 162 that forms the subject matter of my co-pending application Serial No. 185-538, filed January 18, 1938, and consists essentially of angularly spaced pawls 164 which are pivotally mounted on a rotary carrier 166 and enter apertures 168 in the shuttle periphery (Fig. 35) in such alternate fashion that a needle-thread loop 170 (Fig. 32), which is completely passed around the shuttle by its hook 172, need not be twisted, nor is interfered with by the pawls 164, all as described in my above-mentioned co-pending application. The pawls 164 are in permanent engagement with a continuous cam surface 174 (Fig. 35) which is provided by a cylindrical block 176, hereafter called the "cam block", and is so designed that the pawls 164 enter their respective apertures 168 in the shuttle periphery in the above mentioned alternate fashion. To accomplish such cooperation between the cam surface 174 and the pawls 164, the cam block 176 is held non-rotatable, while the pawl carrier 166 is rotated. Rotation of the cam block 176 is prevented by the throat plate 178 which is guided for movement longitudinally of the tack in guideways 180 (Fig. 31) in the work table 182, and drivingly connected with the cam block 176 by any suitable connection such as a pin 184 and a spacer 186 (Figs. 33 to 35), for instance. The throat plate 178 thus indirectly prevents rotation of the cam block 176 in its cylindrical support 188, provided by the horn 51 of the machine.

A ball bearing 190 is interposed between the pawl carrier 166 and the cam block 176. A nut 192, which is threadedly received by the pawl carrier 166, retains an annular shoulder 194 of the latter in permanent engagement with the inner race 196 of said ball bearing 190 (Figs. 2 and 35). On the other hand, the outer race 198 of the ball bearing 190 is retained in permanent engagement with an annular shoulder 200 of the cam block 176 by means of the head 202 of a sleeve 204 which is secured in any suitable manner as at 206 (Fig. 2) to the cam block 176. It is, therefore, obvious that the pawl carrier 166 will move axially together with the cam block 176 as a unit when the latter is axially fed longitudinally of the tack in order to form the various stitches of the tack. A reduced end portion 208 of the sleeve 204 is slidably supported in a boss 212 of the horn 51 of the machine. Splined at 214 to the pawl carrier 166 is one end of a rotatable, but axially immovable, shaft 216 which has its other end journaled in a ball bearing 218 (Fig. 2). The ball bearing 218 is located in a bracket 220 of the horn 51 and held therein by a retainer 222. A bevel gear 224 and a nut 226, both secured to the shaft 216, engage the inner race 228 of the ball bearing 218 and thus prevent axial movement of the shaft 216. The

bevel gear 224 is in permanent mesh with another, identical bevel gear 230 which is mounted on a transverse shaft 232 (Figs. 3 and 8), suitably journalled in suitable bearing brackets 234 and 236, the latter being shown integral with the base frame 50. Also mounted on the transverse shaft 232 is another bevel gear 238 which is in permanent mesh with a larger bevel gear 240, mounted on a horizontal shaft 242 which is suitably journalled in the before-mentioned bearing bracket 236 and another bracket 244 (Fig. 3) which is preferably integral with the base frame 50. The ratio between the bevel gears 240 and 238 is two to one. Also mounted on the vertical shaft 242 is another bevel gear 245 which is in permanent mesh with an identical bevel gear 246, mounted on a horizontal shaft 248 (Fig. 4). The shaft 248 is suitably journalled in the before-mentioned bearing bracket 244 and another bearing bracket 250 which is mounted in the head 52 of the machine. Also mounted on the shaft 248 is a bevel gear 252 which is in permanent mesh with an identical bevel gear 254 that is either drivingly connected, or integral, with the driven member 98 of the sewing clutch 88, 98. Hence, whenever the clutch 88, 98 is engaged, i. e., when the needle shaft is rotated and the needle bar reciprocates, the pawl carrier 166 and the shuttle 160 are rotated through intermediation of shaft 216, bevel gears 224 and 230, shaft 232 (Fig. 3), bevel gears 238 and 240, shaft 242, bevel gears 245 and 246, shaft 248 (Fig. 4) and bevel gears 252, 254. However, inasmuch as the ratio between the bevel gears 240 and 238 (Fig. 3) is two to one, it follows that the shuttle 160 makes two complete revolutions to each rotation of the needle-crankshaft 63, i. e., each reciprocation of the needle bar 54. In other words, the shuttle hook 172 (Fig. 32) catches each loop which is cast by the needle 53 after each second revolution of the shuttle. The reason for rotating the shuttle 160 at twice the speed of the needle crank shaft 63 is fully explained in my before-mentioned co-pending application Serial No. 185,538, and hence requires no explanation here.

While the drawings illustrate a shuttle 160 for the formation of lock stitches such as shown in Fig. 32, it is to be distinctly understood that the rotary looper disclosed in my before-mentioned co-pending application could be used for the formation of chain stitches, if so desired.

Feeding device C for needle and thread handling element

Inasmuch as the work W (Figs. 1 and 2) remains stationary during a tacking operation of the machine, it is necessary simultaneously to move the needle bar-carrying yoke 56 and the shuttle support and drive 162 axially, in order to space the stitches both underlying and overlying, longitudinally of the tack as shown in Fig. 1. More particularly, a vertically reciprocable rack bar 260 (Figs. 3, 4, 8 and 14) is the common driver for simultaneously moving or "feeding" the yoke 56 and the shuttle support and drive 162 axially through intermediation of trains of driving elements to be described. As best shown in Fig. 14, the rack bar 260 is slidable on the machined surfaces 262 of vertically spaced brackets 264 which are mounted in any suitable manner on horizontal flanges 266 of an upright support 268 which is mounted in any suitable manner as at 270 on a side wall of the base frame 50. The rack bar 260 is furthermore guided for

vertical movement by straps 272 (see also Figs. 11 and 12) which are suitably secured to the brackets 264. It appears best from Fig. 14 that the rack bar 260 provides at its opposite ends two racks 274 and 276, one of said racks being adapted to feed the yoke 56 and the other rack being adapted to feed the shuttle support and drive 162. The manner in which the rack bar 260 is power-reciprocated will be described later in the description.

The following structure transmits the movement of the rack 274 to the yoke 56. Cooperating with the rack 274 is a spur gear 278 (Figs. 3 and 4) which is mounted on a horizontal shaft 280, journalled in bearings provided by a suitably mounted bracket 282 and a boss 284 of the machine head 52. Mounted on that end of the shaft 280 which projects into the head 52 is a rocker arm 286 (see also Fig. 2) which is connected with an identical rocker arm 288 on a counter shaft 290 by means of a link 292. The counter shaft 290 is journalled in suitable bearing brackets 294 in the machine head 52 and carries a spur gear 296 which is in permanent mesh with a rack 298, provided in the sleeve 58. Consequently, the sleeve 58 and the yoke 56 are moved axially in opposite directions on reciprocation of the rack 274, as can be readily understood.

The following structure transmits the movement of the rack 276 to the shuttle support and drive 162. Cooperating with the rack 276 is a spur gear 300 (Figs. 3 and 8) which is mounted on a horizontal shaft 302, journalled in bearing brackets 304 and 305 which are mounted on the support 268 and in the horn 51 of the machine, respectively. Mounted on that end of the shaft 302 which extends beyond the bearing bracket 305 is a rocker arm 306 (Figs. 2 and 8) which is connected by a link 307 to another rocker arm 308, mounted on a stub shaft 309 which is journalled in a bearing bracket 310 and a boss 311 of the horn 51. Mounted on the stub shaft 309 between the bearing bracket 310 and the boss 311 is a spur gear 312 which is in constant mesh with a rack 313, provided by the reduced end 208 of the sleeve 204. Hence, the sleeve 204 and the shuttle support and drive 162 are moved axially in opposite directions on reciprocation of the rack 276.

The motion transmitting elements of each of the drives described in the two preceding paragraphs are so coordinated that the yoke 56 with its needle bar 54 as well as the combined support and drive 162 of the shuttle 160 are simultaneously axially moved through equal distances and in the same directions. More particularly, the yoke 56 and the shuttle support and drive 162 are moved or fed to the left as viewed in Fig. 2 on upward movement of the rack bar 260 as viewed in Fig. 14. Conversely, the yoke 56 and the shuttle support and drive 162 are fed to the right as viewed in Fig. 2 on downward movement of the rack bar 260 as viewed in Fig. 14.

Two rotary and alternately operative screw-type feed cams 315 and 316 are called upon for reciprocating the rack bar 260. A common drive, to be described, between the rack bar 260 and the feed cams 315, 316 is in permanent driving relation with the former and in alternate driving relation with the latter. As best shown in Figs. 12 to 15, inclusive, the feed cams 315 and 316 are mounted on vertical shafts 317 and 318, respectively, which are journalled in a swinging frame 320, mounted on the upright support 268.

for oscillation about a vertical shaft 322 (Fig. 15) which passes through extending lugs 324 of said support 268. The swinging frame 320 is prevented from movement axially of the shaft 322 relative to the support 268 by straddling the lugs 324 of the latter in the fashion shown in Fig. 15. The shaft 322 is provided at its upper end with a bevel gear 326 and two spur gears 328 and 330, the latter resting on the swinging frame 320, thus 10 cooperating with a collar 332 to prevent axial movement of the shaft 322 relative to the frame 320. Mounted at the upper end of the shaft 317 (Fig. 14) is a spur gear 334 which rests with its hub 336 on the swinging frame 320. Mounted 15 on the upper end of the shaft 318 is a gear 338 (Fig. 13) which rests on the swinging frame 320. As best shown in Fig. 11, gear 328 is in constant mesh with gear 334, while gear 330 is in constant mesh with gear 338. The ratio between 20 the gears 328 and 334 is one to one, while the ratio between the gears 330 and 338 is one to two. Consequently, on rotation of the bevel gear 326, the feed cam 315 is rotated at the same angular speed as said bevel gear 326, while the cam element 316 is rotated at one-half the angular speed of said bevel gear. Furthermore, the feed cams 25 315 and 316 rotate always in the same directions.

Each of the feed cams 315, 316 has two diametrically opposite rises in each annular groove portion (Figs. 13 and 14), thus forming a continuous cam groove 340 in the feed cam 315 and a continuous cam groove 342 in the feed cam 316.

Permanently meshing with diametrically opposite portions of the bevel gear 326 (see Figs. 3 35 and 4) are smaller bevel gears 344 and 346 which are freely rotatable on a horizontal shaft 348, journaled in bearings provided by bosses 350 of the base frame 50 and head 52 of the machine. The bevel gears 344 and 346 are provided by the 40 driven members 352 and 354, respectively, of a reverse clutch 356, the driving member 358 of which is splined to the shaft 348 and axially movable thereon into alternate engagement with the driven members 352 and 354. The clutch shaft 45 348 carries a bevel gear 360 which is in permanent mesh with a bevel gear 362 that is either drivingly connected, or integral, with the driven member 96 of the main clutch 88, 96. Hence, on engaging the main clutch, the rotary motion of the 50 driving member 88 of said main clutch is transmitted to the driving member 358 of the reverse clutch 356 through intermediation of the bevel gears 362 and 360 which have a ratio of one to one, and the shaft 348.

55 Slidable in vertical guideways 366 and 368 of the upright support 268 (Figs. 11 to 14) are rack-type followers 370 and 372 which are adapted to cooperate with the screw-type feed cams 315 and 316, respectively. The cam element 315 is used 60 for spacing the underlying stitches *a* longitudinally of the tack as shown at *c* in Fig. 1, for instance. Conversely, the cam element 316 is used for spacing the overlying stitches the distance *d* as shown in Fig. 1. The rises 374 of the feed cam 315 are preferably of the harmonic shape shown in Fig. 17. Likewise, the rises 378 of the feed cam 316 are also of harmonic shape as shown in Fig. 19, but are only half as long and half as high as the rises 374 of the feed cam 315. Inasmuch as the followers 370 and 372 have to remain in cooperative engagement with their cam elements 315 and 316, respectively, during the formation of their respective underlying and overlying stitches, the teeth 382 and 384 of said followers 370 and 372, respectively, have to be

of the rhombic cross-sectional shape shown in Figs. 18 and 20, respectively.

As the underlying stitches *a* are the first to be formed, it is the feed cam 315 which is in cooperative engagement with its follower 370 when the machine is started (Figs. 12 and 14). Then, depending on the direction of rotation of the feed cam 315, the follower 370 will either move upwardly or downwardly. As best shown in Figs. 3, 14 and 21, a lever 386, located between the rack 10 bar 260 and the upright support 268, has a hollow shank 388 (Fig. 21) which is journaled in said support 268 and the base frame 50. The lever 386 is provided with an elongated slot 390 in which a rectangular block 392 is slidable. The 15 block 392 is pivoted on the shank 394 of a screw 395 which extends through a vertical slot 395a in the upright support 268 and is secured to the follower 310. The lever 386 is also provided with guideways 396 for a rack 397 which is in permanent mesh with a gear portion 398 of a short shaft 399, rotatable in the hollow shank 388 of the lever 386. Keyed at 400 to the shaft 399 is an index disc 401, having a series of radial serrations 402 one of which registers with a radial 20 tooth 403 of corresponding cross sectional shape, provided by a counter disc 404 which is keyed at 405 to the shank 388 of the lever 386. A nut 406, threadedly received by the shaft 399, is tightened against the index disc 401, thereby not only drawing an annular shoulder 407 of said shaft against an annular shoulder 408 of the lever 386, but also retaining the tooth 403 of the counter disc 404 in registry with its serration 402, thus locking the shaft 399 to the lever 386 for combined rotation. The rack 397 is provided with a head 410, receiving a screw 411, the shank 412 of which serves as a pivot for a rectangular block 413 which projects into an elongated slot 414 in a transverse extension 415 of the rack bar 260 (Fig. 3). It can now be understood that the lever 386 is rocked in a certain direction, depending on the direction of rotation of the feed cam 315, and that the block 413, which rocks with the lever 386, moves the rack bar 260 in the same direction as the direction of movement of the follower 370.

It may be stated in advance that the needle bar 54 and the shuttle 160 assume the rear or home position shown in Fig. 2 when the machine is at rest. Consequently, on starting an operation of the machine, the needle bar 64 and the shuttle 160 will be fed step by step from the illustrated home position in Fig. 2 to the left, such forward feed of the needle bar 54 and shuttle 160 taking place during an upward motion of the rack bar 260, as has been earlier explained. It appears from Figs. 12, 14 and 21 that such upward movement of the rack bar 260 is obtained on rotating the feed cam 315 clockwise as viewed in Fig. 12. In order to rotate the feed cam 315 clockwise as viewed in Fig. 12, the members 352 and 358 of the reverse clutch 356 (Fig. 4) have to be engaged, assuming thereby that the driven member 96 of the main clutch 88, 96 rotates in the direction of the arrow 420 in Fig. 4. The drive between the driven member 96 of said main clutch and the feed cam 315 then comprises the bevel gears 362 and 360, shaft 348, the bevel gears 346 and 326 (Fig. 4), and the gears 328, 334. 70 After the formation of the first line *a* of underlying stitches *a*, i. e., when the needle bar 54 and the shuttle 160 have arrived in their foremost position, the direction of rotation of the feed cam 315 is reversed so as to effect the return

feed of said needle bar and shuttle into the starting or home position shown in Fig. 2, thereby forming the second line *a2* of underlying stitches *a*. To accomplish this, the driving member 358 of the reverse clutch 356 is shifted from engagement with its driven member 352 and into engagement with its driven member 354 under the action of certain controlling means to be described hereafter.

10 As will be more fully explained hereinafter, the construction of the present machine is such that the formation of the underlying stitches *a* is concluded and the formation of the overlying or cover stitches *b* is started when the needle bar 54 and the shuttle 160 are in the starting position shown in Fig. 2. Consequently, it is at this time that the frame 320 is rocked so as to disengage the feed cam 315 from its follower 370 and to engage the feed cam 316 with its follower 372. Secured to the follower 372 is a screw 421 (Fig. 12) which extends through a vertical slot 422 in the upright support 268 and serves as a pivot for a rectangular block 423 which is received in an elongated slot 424 of a lever 425, having a hollow shank 426 which is journaled in the support 268 and a wall of the base frame 50. The lever 425 is provided with guideways 427 for a rack 428 which is in permanent mesh with a gear portion 429 of a short shaft 430, received in the hollow shank 426. The shaft 430 has keyed thereto at 431 an index disc 432, having a plurality of radial serrations 433, one of which registers with a radial tooth 434 of corresponding cross sectional shape which is provided by a counter disc 435. This counter disc 435 is keyed at 436 to the shank 426 of the lever 425. A nut 437 is threadedly received by the shaft 430 and tightened against the index disc 432, thereby not only retaining an annular shoulder 438 of said shaft in permanent engagement with an annular shoulder 439 of said shank 426, but also retaining the tooth 434 in registry with its serration 433, thus locking the shaft 430 to the lever 425 for combined rotation. As best shown in Fig. 14, the lever 425 is located between the rack bar 260 and the upright support 268. The rack 428 is provided with a lateral extension 440 (Fig. 12) which receives a screw 441, the shank 442 of which serves as a pivot for a rectangular block 443, received in an elongated slot 444 in a transverse extension 445 of the rack bar 260 (Fig. 3). Hence, when the rotating feed cam 316 is in cooperative engagement with its follower 372, the movement of the latter is transmitted to the rack bar 260 through intermediation of the rectangular block 423, the pivotally mounted lever 425 and the rectangular block 443.

More particularly, clockwise rotation of the feed cam 316 as viewed in Fig. 12 will cause upward motion of the rack bar 260, i. e., cause a forward feed of the needle bar 54 and shuttle 160 from the starting position shown in Fig. 2 for the spacing *d* of the overlying stitches *b* (Fig. 1). Rotation of the feed cam 316 in the opposite direction will, conversely, cause a downward movement of the rack bar 260 and a consequent return feed of the needle bar 54 and the shuttle 160 into the home position shown in Fig. 2. The reversal of the feed cam 316 is accomplished, under the automatic control of means to be described later, by shifting the driving member 358 of the reverse clutch 356 from engagement with one of its driven members (352, 354) and into engagement with the other driven member. Because both of the feed

cams 315 and 316 are carried by the swinging frame 320 (Fig. 12), it stands to reason that only one of the followers 370, 372 may at any time be in engagement with its feed cam 315 or 316, respectively, thereby effecting movement of the 5 rack bar 260 under the control of either feed cam without interference from the other feed cam which is then out of engagement with its follower.

It can also be understood that the reciprocatory motion of the rack bar 260 is comparatively fast when under the control of the feed cam 315 (for the underlying stitches), because the block 392 (Fig. 21) is comparatively close to the pivot axis 450 of the lever 386, the rocking motion of which 15 is transmitted to the rack bar 260 by the block 413 in form of a reciprocatory motion. On the other hand, the reciprocatory motion of the rack bar 260 is comparatively slow when under the control of the feed cam 316 (for overlying 20 stitches), because the block 423 (Fig. 12) which is carried by the follower 372, is comparatively distant from the pivot axis 451 of the lever 425, the rocking motion of which is transmitted to the rack bar 260 by the block 443 in form of a 25 reciprocatory motion. The difference between the different speeds of reciprocation of the rack bar 260 under the different controls of the feed cams 315 and 316 is even increased by reason of the fact that the former rotates twice as fast 30 as the latter, and the rises 374 of the feed cam 315 are moreover twice as high as the rises 378 of the feed cam 316.

The speed at which the rack bar 260 reciprocates may be varied by sliding either the rack 428 35 or the rack 397 in the guideways 427 and 396, respectively. Hence, if it is desired to vary the rate of reciprocation of the rack bar 260, while the same is under the control of the feed cam 315, the rack 397 is shifted in its guideways 396 40 by rotating the shaft 399 (Fig. 21) which has its gear portion 398 in permanent mesh with said rack. This is accomplished by loosening the nut 406 sufficiently to permit axial withdrawal of the index disc 401 until the presently registering serration 402 of the latter clears the tooth 403 of the counter disc 404, whereupon the shaft 399 together with the index disc 401 may be turned relative to the counter disc 404 and, hence, relative to the lever 386. Thereafter, the index disc 401 is again locked to the counter disc 404 by the nut 406, whereby a new serration 402 will be in registry with the tooth 403. Likewise, if it is desired to vary the rate of reciprocation of the rack bar 260 while the same is under the control of the feed cam 316, the just described operation is performed on the index disc 432 (Fig. 12) in order to shift the rack 428 in its guideways 427 into the desired position.

In order to assure instantaneous mesh between the feed cams 315, 316 and their respective followers 370 and 372, the continuous cam grooves 340 and 342, respectively, of the former, as well as the teeth of the latter, are preferably of the conical cross-section shown in Fig. 16.

Needle vibrating device D

It appears from Fig. 1 that the needle 53 has to be laterally vibrated in order to form the overlying stitches *b*. This is accomplished by oscillating the yoke 56 (Fig. 2) about the axis 455 while the same is simultaneously fed step by step for spacing the overlying stitches the distance *d* (Fig. 1) longitudinally of the tack. To 75

this end, the yoke 56 is connected with a rocking lever 456 (Figs. 2, 3 and 4) by means of a link 457. The rocking lever 456 is provided by a sleeve 458 (Fig. 36) which is journalled in a boss 459 of the head 52 of the machine. Telescoping with the sleeve 458 and freely rotatable therein is a stub shaft 460 which has one end journalled in a bearing bracket, provided by the head 52 of the machine. Mounted on the stub shaft 460 is a rocker arm 462 which is pivotally connected at 463 with an arm 464, carrying a follower 465 which cooperates with a cam groove 466 in a disc 467, mounted on a shaft 468 which is journalled with one end in a boss 469 of the head 52 and 15 with its other end in a sleeve portion 470 of the driving member 471 of a needle-vibration clutch 472. The sleeve portion 470 of the driving clutch member 471 is journalled in a bearing bracket 473 in the head 52 of the machine. The 20 follower arm 464 is provided with a rectangular slot 474 wherein a rectangular block 475 is slidably received. The block 475 is freely rotatable on the shaft 468. Hence, the block 475 in the slot 474 forms a floating pivot for the follower 25 arm 464. The cam disc 467 is drivingly connected, or integral, with the driven member 476 of the sewing clutch 472 which may be of the same construction and operation as that disclosed in Figs. 5, 6 and 7. The driving clutch member 471 is 30 drivingly connected, or integral, with a bevel gear 478 which is in permanent mesh with a bevel gear 479, mounted on the shaft 248. The ratio between the bevel gears 478 and 479 is two to one so that, on engagement of the sewing clutch 35 88, 98 and of the vibration clutch 472, the cam disc 467 makes one half revolution to each complete reciprocation of the needle bar 54 and to every two revolutions of the shuttle 160. The rocker arm 462 is provided with a semi-cylindrical 40 cal sleeve 480 which is in constant coupling engagement with a similar semi-cylindrical portion 481 of the sleeve 458 (Fig. 36). Hence, when the clutch 472 is engaged, the needle bar carrying yoke 56 is oscillated through intermediation of 45 link 457, rocker arm 456, coupling 481 and 480, rocker arm 462, follower arm 464 and cam disc 467. More particularly, the rocker arm 456 is provided with arcuate guideways 483 which are concentric to the pivot connection between the 50 link 457 and the yoke 56 (Fig. 3) when the latter is in the home position in which the needle bar is disposed vertically. Adjustable within the arcuate guideways 483 of the rocker arm 456 is a sliding block 484 to which the link 457 is pivoted 55 as at 485. The sliding block 484 may be secured to the rocker arm 456 in any adjusted position within the guideways 483 in any suitable manner. Thus, the amplitude of oscillation of the yoke 56 and, consequently, the spacing *e* of the 60 overlying stitches *b* (Fig. 1), may be varied as desired. It is even possible to prevent oscillation of the yoke 56 in spite of rotation of the cam disc 467, simply by shifting the sliding block 484 into coaxial alignment with the pivot axis 65 of the rocker arm 456.

As best shown in Fig. 36, the sleeve 458 is provided with an annular groove 486 into which projects the forked end 487 of the member 68 (Fig. 2) which is fed together with the yoke 56 longitudinally of the tack. The rocker arm 456 is thus coupled by the member 68 to the yoke 56 for combined movement longitudinally of the tack. Such movement of the rocker arm 456 does not interfere with the drive of the latter by the axially immovable sleeve 480 because the coupling

portions 480 and 481 of said sleeves permit relative axial movement therebetween.

Thread severing and clamping device E

Referring more particularly to Figs. 2, 8 and 31 to 35, inclusive, a star wheel 490, having equiangularly spaced radial arms 492, is pivotally mounted at 493 to the throat plate 178. Also mounted on the throat plate 178, is a thread cutter 494, a spacer 495 and a thread clamp 496. More particularly, the cutter 494, which is of the shape illustrated in Figs. 32 and 33, is nearest to the throat plate 178 while the spacer 495 is intermediate said cutter and the thread clamp 496. The thread clamp 496 is in reality a leaf spring, and the spacer 495 has an arcuate surface 497 which defines, together with the cutter 494 and the clamp 496, a groove 498 through which the arms 492 of the star wheel 490 are adapted to pass in the manner shown in Figs. 33 to 35, inclusive. It can also be observed from Figs. 33 and 34 that each arm 492 will traverse the throat opening 499 in the throat plate 178 before entering the groove 498.

The operation of the thread cutter and clamp is as follows: During the formation of the last stitch *b* (Fig. 1), but prior to the completion thereof, the needle-thread loop 170 assumes during its passage around the shuttle 160 the momentary position illustrated in Fig. 32, and it is at this time that the star wheel 490 is indexed a distance equal to the angle between consecutive arms 492. Each of these arms 492 is provided with fingers 500 which are so spaced apart that they catch the forward leg 501 of the needle-thread loop 170 and the bobbin thread 502 in the fashion shown in Fig. 32 when one of these arms 492 has been advanced from the position 492a (Fig. 34) into the momentary position shown in Fig. 32. During the continued advance of this arm from the position shown in Fig. 32 into the position 492b, the same draws the caught threads into the groove 498, whereby the shear edges 503 of the cutter 494 cooperate with said arm 492 to sever the needle thread loop and the bobbin 45 thread. Hence, the needle thread which has been used up in the formation of the lock stitches in the work *W*, is severed from the supply thread at the shearing edge 503 of the cutter 494, leaving a short length of upper or needle thread extending from the last stitch hole in the work *W*. Hence, there is no complete lock stitch in the last hole stitched into the work by the needle. Likewise, the bobbin thread, which has been used up in the formation of the lock stitches, 55 is severed at the shearing edge 503, leaving a short length of under or bobbin thread depending from the hole in which the last lock stitch has been completed (Fig. 32). The leading or severed end of the bobbin thread supply 502 between the arm 492 and the clamp 496 is, furthermore, clamped between the arm 492 and the clamp 496 in such manner that the same will be carried against the work by the first loop of needle thread which has been passed around the shuttle 35 160 on the first reciprocation of the needle 53 during the next cycle of operation of the machine.

In order to index the star wheel 490 at the end of each tacking operation of the machine, a reciprocable pawl 505 is slidable on a machined flat surface 507 of the cam block 176 (Figs. 31 to 35), and rotatable about a pivot 508 which is guided for linear movement in a groove 508a in said machined surface 507 of the cam block

176. The pawl 505 is provided with cam surfaces 508, 509, 510 and 511. The cam surfaces 508 to 510, inclusive, are adapted to cooperate with a pin 513 which projects from the cam block 176, 5 while the cam surface 511 is adapted to cooperate with a pin 514 which projects also from the cam block 176. In the full line position 505a of the pawl as shown in Fig. 33, the same is held in engagement with a machined shoulder 515 of the 10 cam block 176 by means of the floating pivot 506 and through cooperation between the cam surface 510 and the pin 513. It appears also from Fig. 33 that the pawl in the position 505a locks the star wheel 490 against rotation in 15 either direction. On moving the pawl from the position 505a to the right as viewed in Fig. 33, its cam surface 508 will engage the pin 513, whereby said pawl is rocked into the dot and dash line position 505b (Fig. 34), but not until 20 said pawl has been sufficiently withdrawn into the full line position 505c (Fig. 34) to clear the star wheel 490 when being rocked into said dot-and-dash line position 505b. Now, when the pawl 505 is moved forwardly, i. e., to the left 25 in Fig. 34, the same is locked against any clockwise rotation as viewed in Fig. 34 until said pawl projects underneath the nearest arm 492 of the star wheel 490 as shown in the dot-and-dash line position 505d of the pawl in Fig. 33. More 30 particularly, the pawl 505 is locked against rotation in any direction during its advance from the position 505b into the position 505d due to the cooperation between its cam surfaces 509 and 511 and the pins 513 and 514, respectively, 35 and by reason of the fact that the floating pivot 506 projects between the pins 513 and 514 until the pawl projects underneath the nearest arm 492 of the star wheel 490. Continued movement of the pawl 505 from the position 505d into the 40 full line position 505a (Fig. 33) will result in a rocking motion of the same in a clockwise direction as viewed in Fig. 33 due to the cooperation between the cam surface 510 and the pin 513. Thus, the star wheel 490 is indexed once during 45 one reciprocation of the pawl 505.

For reciprocating the pawl 505, a link 520 is connected thereto at 506 (Fig. 35). This link 520 is also pivotally connected at 521 with a bell crank lever 522 which is pivotally mounted at 50 523 (Figs. 8, 9 and 10) on a rack 524, movable in guideways 525 which are provided by a bracket 526 of the horn 51 of the machine and gib plates 527. Interposed between the depending arm 528 (Fig. 3) of a cam follower 529 (Fig. 25) and the 55 other arm 530 of the bell crank lever 522, and connected thereto by universal joints 531 (Fig. 8), is a link 532. Meshing with the rack 524 is a spur gear 533 (Figs. 9 and 10) which is keyed as at 534 on a stub shaft 535, journaled in the 60 bracket 526. Mounted on one end of the stub shaft 535 is a rocker arm 536 which is connected by a link 537 with one arm 538 of the double arm rocker 306 (Figs. 2 and 8). Inasmuch as the two arms of the lever 306, which are connected with the links 307 and 537, are identical and diametrically opposite each other, and inasmuch as the gears 312 and 533 are also identical, it appears, particularly from Fig. 2, that the rack 524 with the bell crank lever 522 and 65 the link 520 are moved through the same distances and in the same directions as the shuttle support and drive 162 when the latter is fed in either direction by either of the feed cams 315 or 316. Inasmuch as the star wheel 490 as well as the cutter 494 and thread clamp 496 are car-

ried by the throat plate 178 and, hence, also movable together with the shuttle support and drive 162, the elements shown in Figs. 33 and 34 will be maintained in their relative positions and no relative movement between any of these elements takes place while the shuttle support and drive is fed. However, at a certain time in the cycle of operation of the machine and by means of a cam to be described hereafter, the follower 529 will be rocked at first counterclockwise as 10 viewed in Fig. 25 so as to withdraw the pawl 505 from the full line position 505a in Fig. 33 to the dot-and-dash line position 505b in Fig. 34. Shortly thereafter, the pawl 505 is rocked forwardly into its normal position 505a again, 15 thereby indexing the star wheel 490 for a cutting and clamping operation which takes place in the previously explained manner.

Control F

20

The present machine is so constructed as to form the tack illustrated in Fig. 1. This particular tack has four superimposed lines *a*1 to *a*4 of underlying stitches *a* and one row *b*1 of overlying or covering stitches *b*. For clarity's 25 sake, Fig. 1 shows the four lines *a*1 to *a*4 of underlying stitches *a* side by side, rather than superimposed as they are in reality. Hence, when the machine is started with the needle element 53 and the shuttle element 160 in the home 30 position shown in Figs. 1 and 2, these elements are first advanced step by step in the direction of the arrow 550 (Fig. 1), while at the same time cooperating to form the first line *a*1 of underlying stitches *a*. The step by step forward feed of the elements 53 and 160 in the direction of the arrow 550 is then reversed and these elements are moved step by step in the direction of the arrow 552 (Fig. 1) to form the second line 35 *a*2 of underlying stitches *a*. On arrival in the 40 home position, the direction of feed of these elements is again reversed to a step by step forward feed for the formation of the third line *a*3 of underlying stitches *a*, said feed to be reversed again to a step by step return feed for the 45 formation of the fourth and last line *a*4 of underlying stitches *a*. The alternate forward and return feeds of the elements 53 and 160 up to this point in the cycle of operation of the machine has been derived from the cam element 50 315, resulting in the comparatively wide spacing *c* of the underlying stitches *a* (Fig. 1). For the following formation of the narrowly spaced overlying stitches *b*, the step by step forward feed in the direction of the arrow 550 is derived from 55 the feed cam 316 (Fig. 13). However, before the needle descends for the first time during this forward feed, the same is shifted to one side (right side in Fig. 1) of the longitudinal axis of the tack a distance which is one-half the width 60 *e* of the overlying stitches *b*. Thereafter, the needle is shifted or vibrated the full width *e* during consecutive needle reciprocations, as can be readily understood. Also, each step during the forward feed of the needle and shuttle elements 53 and 160 takes place on each second 65 needle reciprocation, with the result that each second overlying stitch extends at right angles to the longitudinal axis of the tack. This is by reason of the fact that the feed cam 316 (for the overlying stitches) is rotated at one-half the angular speed of the feed cam 315 (for the underlying stitches). As soon as the overlying 70 stitches *b* are formed, the direction of feed of the elements 53 and 160 is again reversed. At 75

this point in the cycle of operation of the machine, the thread cutter and clamp performs its operation, and the needle ceases to reciprocate and, hence, no longer cooperates with the shuttle 160, with the result that no stitches are formed during the following return feed of the elements 53 and 160. Also, the needle ceases to vibrate at this point in the cycle of operation of the machine. The following last return feed of the elements 53 and 160 into the home or starting position remains under the control of the feed cam 316, with the result that these elements are returned to home position in intermittent steps of the length d (Fig. 1).

It follows from the preceding description that the various automatic operations for the formation of a tack start and end at the times when the feed of the elements 53 and 160 is reversed.

A horizontal main cam shaft 555 (Figs. 3, 11 and 25) is rotatably supported in bearings, provided by the base frame 50 as best shown in Fig. 11. Journaled in bearings, also provided by the base frame 50, is a countershaft 556 (Figs. 3 and 25) on which are mounted a plurality of followers which cooperate with certain cams on the cam shaft. Also journaled in bearings, provided by the base frame 50, is another countershaft 557 (Figs. 3 and 25).

Mounted on the cam shaft 555 is a cam disc 558 (Figs. 25 and 27) with which cooperates the follower portion 559 of a rocker 560, freely rotatable on the countershaft 556. A rocker 561, which is mounted on one end of a stub shaft 562 (Figs. 3 and 4) is connected with the rocker 560 by a link 563. The stub shaft is suitably journaled in bosses 564 of the machine head 52 and has the shifter 477 for the vibration clutch 472 keyed or otherwise secured thereto. A spring 565 retains the follower portion 559 of the rocker 560 in permanent engagement with the cam disc 558. Hence, on rotation of the cam disc 558, the shifter 477 will be rocked into clutch disengaging position by said cam disc 558.

Also mounted on the cam shaft 555 is a cam disc 570 (Figs. 25 and 28) with which cooperates a follower portion 571 of a rocker 572, keyed or otherwise secured to the countershaft 556. A spring 573 retains said follower portion 571 in permanent engagement with the cam disc 570. The earlier described shifter 122 (Fig. 4) for the "sewing" clutch 88, 98 has an extending arm 574 which is connected with the rocker 572 by a link 575. Hence, on rotation of the cam disc 570, the shifter 122 will be rocked into clutch disengaging position by said cam disc 570.

Also mounted on the cam shaft 555 is a cam disc 580 with which cooperates the follower portion 581 of a rocker 582 (Figs. 25 and 29), freely rotatable on a sleeve portion 586 of a rocker 587 which is in turn freely rotatable on the countershaft 556. A spring 583 retains said follower portion 581 in permanent engagement with the cam disc 580. The earlier described shifter 158 (Fig. 4) for the "main" clutch 88, 96 has an extending arm 584 which is connected with the rocker 582 by a link 585. Hence, on rotation of the cam disc 580, the shifter 158 will be rocked into clutch disengaging position by said cam disc 580.

Mounted on one end of the countershaft 556 on the outside of the base frame 50 is a lever 576 (Fig. 25) which is provided with a pin 576a that projects into a forked end 577a of a lever 577, pivotally mounted at 578 to a side wall of the base frame 50 and connected with a foot treadle (not shown) by means of a rod or other suitable con-

nexion 579. Hence, on stepping on the foot treadle, the connection 579 is moved downwardly, causing a rocking of the shifter 122 for the sewing clutch 88, 98 downwardly as viewed in Fig. 5, thereby causing clutch engagement. Inasmuch as a projecting lug 122a of the shifter 122 overlaps a projecting lug 158a (Fig. 4) of the shifter 158, it stands to reason that the latter is also rocked into clutch engaging position simultaneously with the shifter 122. The manual engagement of the sewing clutch 88, 98 and of the main clutch 88, 96 is not obstructed by the cam discs 570 and 580, respectively, as their respective followers 571 and 581 may be rocked into clutch engaging position when the cam discs 570 and 580 are in the home position shown in Figs. 28 and 29. Hence, the manual engagement of the sewing clutch 88, 98 and of the main clutch 88, 96 merely brings the followers 571 and 581 into position for cooperation with their respective cam discs 570 and 580 for disengagement of these clutches at predetermined points in the cycle of operation of the machine.

Also mounted on the cam shaft 555 is a cam disc 590 with which cooperate two angularly spaced follower portions 591 of a rocker 592 (Figs. 25 and 30) which is freely rotatable on a stub shaft 592a, suitably mounted in a boss 592b of the base frame 50. The rocker 592 is provided with a roller-shaped end 593 which projects into a notch 594 in a shaft 595 which is axially slideable in bearings, provided by the base frame 50 (Fig. 4). Mounted on the shaft 595 is a shifter fork 595a which projects into an annular groove 596 in the axially slideable driving member 358 of the reverse clutch 356. Hence, on rotation of the cam disc 590, the driving member 358 of the clutch 356 is alternately shifted into engagement with the driven members 352 and 354 thereof. It will be noted from Fig. 30 that, due to the equiangular spacing of the cam lobes 590a and the provision of the properly spaced follower portions 591 of the rocker 592, the latter requires no spring in order to be retained in permanent engagement with its cam disc 590.

Also mounted on the cam shaft 555 is a disc 600, having in its periphery a continuous cam groove 601 with which cooperates a follower 602 on one arm 603 of a lever 604 (Figs. 4 and 11) which is pivotally mounted at 605 on spaced lugs 606 of the upright support 268. The other arm 607 of the lever 604 is floatingly pivotally connected at 608 (Fig. 11) with the swinging frame 320 that carries the feed cams 315 and 316. Hence, on rotation of the cam disc 600, the feed cams 315 and 316 are alternately brought into cooperative engagement with their respective followers 370 and 372.

Also mounted on the cam shaft 555 is a cam disc 610 with which cooperates the earlier mentioned follower 529 that is freely rotatable on the countershaft 557. A spring 611 retains the follower 529 in permanent engagement with the cam disc 610. Hence, on rotation of the cam disc 610, the pawl 505 is first retracted from the position 505a in Fig. 33 into the dot-and-dash line position 505b in Fig. 34, and is then advanced again into the position 505a, thereby indexing the star wheel 490 for the performance of a thread cutting and clamping operation.

Inasmuch as the operations of the various operating devices of the machine are under the control of the just described cams and must start and end at the reversals of the feed of the needle and shuttle, as earlier explained, the cam shaft 555

has just been indexed on arrival of the needle and shuttle in their extreme end positions of feed. To this end, a ratchet 615 (Figs. 11 and 25) is mounted on the cam shaft 555. Cooperating with the ratchet 615 is a spring-urged pawl 616, carried by a frame 617 which is freely rotatable on said cam shaft. The frame 617 is connected with a plunger 618 by two links 619. The plunger 618 is reciprocable in a boss 620 of the base frame 50, and is normally urged by a spring 621 (Figs. 3 and 25) into the uppermost position shown in Figs. 25 and 26 in which the foot 622 of said plunger engages the boss 620 (Fig. 3).

Splined at 623 to the shaft 348 (Figs. 4 and 25) is an axially movable disc 624 which is provided with two cams 625 and 626 and an annular groove 627 therebetween. Projecting into the annular groove 627 is a shifter fork 628 which is axially slideable on the countershaft 595 and provided with a socket 629 to receive the roller-shaped end 630 of the earlier mentioned rocker 587 (Fig. 25). Suitably mounted on the sleeve portion 586 of the rocker 587, which is freely rotatable on the countershaft 556, is a fork 631 which slidably receives a block 632 (Fig. 26) between its legs 633 and 634. The block 632 is pivoted at 635 to an arm 636 of a rocker 637 which is freely rotatable on the countershaft 557. The other arm 638 of the rocker 637 is provided with an extending pin 639 which is adapted alternately to cooperate with rotatable fingers 640 and 641.

As best shown in Figs. 11 and 22, the finger 640 is integral with a sleeve 642 which is rotatable about an inner sleeve 643 that provides the other finger 641. The inner sleeve 643 is in turn freely rotatable on the cam shaft 555. More particularly, the end of the outer sleeve 642 is cut to the level of the surface 644 of the finger 640 (Fig. 11), thereby providing a part-annular shoulder 645 (Figs. 11 and 22) on which the finger 641 of the inner sleeve may rest in any angular position within a preassigned range relative to the other finger 640. The fingers 640 and 641 are thus located in the same plane regardless of their variable angular relative positions. The inner sleeve 643 is splined at 646 to an index disc 647 which is accessible at the outside of the base frame 50 and has one of a plurality of radial serrations 648 (Fig. 23) in registry with a tooth 649 of a counter disc 650 which is keyed at 651 to the outer sleeve 642. A nut 652, threadedly received by the inner sleeve 643, not only retains the tooth 649 in registry with its serration 648 and thus locks the sleeves 642 and 643 for combined rotation on the cam shaft 555, but also cooperates with a gear 653 of said outer sleeve and an outer sleeve bearing 654 in the base frame to prevent axial movement of said interlocked sleeves. The gear 653 is in constant mesh with a gear 655 (Fig. 25) which is keyed or otherwise secured to the countershaft 557. Another gear 656 is also mounted on the countershaft 557 and in constant mesh with a gear 657 which is freely rotatable, but axially immovable, on the cam shaft 555. Permanently meshing with the gear 657 is a gear segment 658 (Figs. 3 and 25) which is secured to, or preferably made integral with, the rocking lever 425 which is a driving link between either feed cam 315 or 316 and the rack bar 260 (Fig. 14), as has been earlier explained. The ratio between the pairs of gears 657, 656 and 655, 653 is 1 to 2 and 2 to 1, respectively, with the result that the gear 653 is ro-

tated at the same angular speed, and in the same direction, as the gear 657.

It follows from the preceding description that during step by step longitudinal movement of the rack bar 260 (Fig. 14) in either direction and, under the control of either feed cam 315 or 316, the arms 640 and 641 are intermittently rotated about the common axis of their sleeves 642 and 643 (Fig. 11). One of these arms is thereby gradually brought into engagement with the pin 635 (Figs. 25 and 26) rocks the fork 631 and rocker 587 from the normal position shown in Fig. 3 into either one of two angularly displaced positions. Such rocking of the rocker 587 results in axial shifting of the disc 624 so that one of its cams 625 or 626 is brought into alignment with the plunger 618. Which one of the cams 625 or 626 is brought into alignment with the plunger 618 depends solely on the direction in which the gear segment 658 rocks. Shortly after one of the cams 625 or 626 has been brought into alignment with the plunger 618, its cam lobe 660 or 661, respectively, moves into engagement with said plunger and knocks the same downwardly with a quick power stroke, thereby indexing the cam shaft 555 through intermediation of the pawl 616 and the ratchet 615. Overtravel of the ratchet 615 is prevented by the foot 622 of the plunger 618 which is engaged in its momentary lowermost position by the nearest ratchet tooth just when the indexing of the ratchet is completed. After indexing the ratchet 615, the plunger 618 is returned to its normal up position and the pawl 616 conditioned for the next indexing operation, by means of the spring 621 (Fig. 3). While the ratchet 615 and, hence, the cam shaft 555, is being indexed, the cam disc 590 (Figs. 25 and 30) quickly reverses the drive of the feed cams 315 and 316 through intermediation of the rocker 592, shaft 595, shifter fork 596 and reverse clutch 356 (Fig. 4). However, it may be stated in advance that the reversal of the feed cams 315 and 316 is not every time followed by an immediate intermittent feed of the needle and shuttle elements 53 and 160 in the reverse direction. An immediate intermittent feed of the elements 53, 160 takes place only after the presently operative teeth 382 or 384 of the followers 370 or 372, respectively, have just completely passed through the rises 374 or 378, respectively, of the feed cams 315 or 316, respectively, when the reversal of the direction of rotation of the latter takes place. Only if this condition prevails does the arm 640 or 641, whichever engages the pin 639 at the time, rotate away from the latter immediately on reversal of the feed cams 615, 616 and permits the axial shifting of the disc 624 into its normal position (Fig. 3) in which the plunger 618 is out of the path of the cam lobe (660 or 661) long before the disc 624 completes another revolution and the same cam lobe passes through its "knock-down" position again. In the normal position of the disc 624 (Fig. 3), the plunger 618 is in alignment with the annular groove 627 of said disc and, hence, out of cooperative alignment with either of the cams 625 or 626. Therefore, inasmuch as there are several reversals of the feed cams 315 and 316 during one cycle of operation of the machine which are not immediately followed by an intermittent feed of the needle and shuttle, provisions are made for delaying the spring-return of the plunger 618 after each indexing of the ratchet 615 until the first intermit- 75

tent feed of the needle and shuttle after each reversal of the feed cams 315 and 316 has taken place. To this end, a latch member 670 (Figs. 25, 26 and 26a) is pivotally mounted at 671 on the boss 620, and is provided with a notch 672 and a shoulder 673 which extends transversely to said notch. The plunger 618 carries a pin 674 which extends through a vertical slot 675 of the boss 620. A spring 676 normally urges the latch member 670 in a clockwise direction as viewed in Fig. 26a. It appears from Fig. 26 that, on shifting either cam 625 or 626 into alignment with the plunger 618, a follower portion 677 of the latch member is located to the right of the cam 625 or in alignment with the annular groove 627, respectively, i. e., out of cooperative alignment with either cam 625 or 626. Therefore, when either cam lobe 660 or 661 knocks the plunger downwardly for an indexing of the ratchet 615, the pin 674 travels along the latch surface 673 and reaches the entrance to the notch 672 just when the cam lobe is about to clear the plunger. The latch member 670 is then released by the pin 674 for clockwise rotation as viewed in Fig. 26a under the tension of the spring 676, whereupon the slightly inclined slot 672 receives said pin 674 and further withdraws the plunger a slight distance and locks it in withdrawn position so that the same completely clears the cam lobe should the latter pass by the plunger again while the same is still in alignment therewith. When the pin 674 of the plunger 618 projects into the notch 672 of the latch member 670, the follower portion 677 of the latter is spaced from the axis of the cam shaft 555 approximately the same distance as the concentric peripheries of the cams 625 and 626. Thereafter, whenever the first intermittent feed of the needle and shuttle takes place, even when the disc 624 makes more than one revolution after the reversal of the feed cams 315 and 316, the disc 624 is spring-urged into its normal position (Fig. 3), and the latch member 670 is then in alignment with one of the cams 625 or 626, depending on the direction of axial movement of the disc 624 into its normal position. It is then that the cam lobe of the respective cam 625 or 626, whichever happens to be in alignment with the latch member 670, cooperates with the follower portion 677 of said latch member and forces the latter into the position shown in Fig. 26 in which the pin 674 is without the confines of the notch 672, whereupon the plunger is spring-returned into its normal or uppermost position, ready for a new down stroke by the other of the cams 625, 626 when the other of the arms 640, 641 rocks the rocker 637 in the opposite direction. The latch member 670 is locked in the position shown in Fig. 26a by the pin 674 until the plunger 618 is again struck-down.

The rocker 587 is floatingly pivotally connected at 680 with a rod 681 (Fig. 26) which extends into an annular recess 682 in a boss 683 of the base frame 50. The rod 681 is provided with a collar 684 against which bear equally pre-loaded compression springs 685 and 686 that tend to retain the rocker 587 and, hence, the cam disc 624 in the normal position shown in Figs. 3 and 26 through intermediation of the shifter fork 628.

presser foot (not shown). While the machine is at rest, the cam shaft with its various cams and the arms 640, 641 assume the position shown in Fig. 25. It will be observed from this figure that the cam 626 of the disc 624 is in alignment with the plunger 618 which is, however, locked in its lowermost position by the latch member 670. Also, the driving member 358 (Fig. 4) of the reverse clutch 356 is in engagement with the driven member 352 thereof, conditioning the feed cams 315, 316 for clockwise rotation as viewed in Fig. 12. The follower 370 is furthermore in engagement with its feed cam 315 so that a forward feed of the needle 53 and shuttle 160 for the formation of underlying stitches *b* will immediately take place on engagement of the main clutch 88, 96, (Fig. 4). This clutch is engaged simultaneously with the manual engagement of the sewing clutch 88, 98 in the earlier explained manner. Consequently, on manual engagement of the sewing clutch 88, 98 by means of the non-disclosed foot treadle, the needle and shuttle cooperate to form the first line *a1* of underlying stitches *a*, whereby each intermittent forward feed of the needle and shuttle takes place during a relatively small portion of one revolution of the needle crank 66, i. e., between the formation of consecutive underlying stitches *a*. When the the needle and shuttle are fed from the stitch *a5* to the stitch *a6* (Fig. 1), the finger 641 (Figs. 3 and 25) rocks the rocker 637 so that the cam 625 is shifted from its normal position (Fig. 3) into alignment with the plunger 618, which is therefore ready to be knocked-down by the cam lobe 660. Before this takes place however, the needle has completed the last stitch *a6* in the line *a1*. The direction of rotation of the feed cams 315 and 316 is then reversed by causing disengagement of the driving member 358 of the reverse clutch 356 from the driven member 352 thereof, and engagement of the former with the other driving member 354. The jaws of the clutch members 352, 354 and 358 are shown in section in Fig. 37. The driving member 358 is shown in engagement with the driven member 352, with both members rotating in the direction indicated by the arrows 690. Hence, the driven member 354 idles in the opposite direction as indicated by the arrow 691. On shifting the driving member 358 into engagement with the driven member 354, their active shoulders 692 and 693, respectively, approach each other at the same speed. By spacing the driven members 352 and 354 as shown in Fig. 37 and by timing the shifting of the driving member 358 so that the same starts to shift just as the jaws of both driven members assume the momentary relative position shown in Fig. 37, the shoulders 693 of the driven member 354 will engage the shoulders 692 of the driving member 358 in the dot-and-dash line position in Fig. 37 just when the latter has cleared the jaws of the other driven member 352. In so doing, the drive of the feed cams 315, 316 is never interrupted and the reversal of said cams is instantaneous.

The needle and shuttle now travel backward step by step into the home position, thereby forming the second line *a2* of underlying stitches *a*. On arrival in the home position, and after previous rocking of the rocker 637 (Figs. 3 and 25) during the last intermittent return feed by the finger 640 and consequent alignment of the cam 626 with the plunger 618 and indexing of the ratchet 315, the driving member 358 of the reverse clutch 356 is again shifted to forward feed

Mode of operation of machine

Assuming the machine to be adjusted for producing the tack illustrated in Fig. 1, the material or work is first clamped to the work table by any conventional manually releasable, spring-urged

70
75

70
75

for the formation of the third line *a3* of underlying stitches *a*. Another reversal of the feed cams takes place after the formation of the third line *a3* of stitches in the same manner as described with respect to the first line *a1* of stitches, whereupon the last line *a4* of underlying stitches is formed. After previous tripping of the rocker 637 (Figs. 3 and 25) during the last intermittent return feed in the formation of the stitch line *a4* 10 by the finger 640, and consequent alinement of the cam 626 with the plunger 618, the cam lobe 661 knocks said plunger down and indexes the ratchet 615 and the cam shaft 555 just when the needle and shuttle arrive in home position.

15 This time, the indexing of the cam shaft has not only brought one of the lobes 700 of the cam disc 558 (Figs. 25 and 27) into cooperative engagement with the follower portion 559 of the rocker 560, but has also brought one of the inclined portions of the groove 601 in the cam disc 600 into cooperative engagement with the follower 602 of the lever 603, resulting in immediate engagement of the needle vibration clutch 472 (Fig. 4) and immediate rocking of the frame 320 20 so as to bring the feed cam 316 into cooperative engagement with its follower 372 for the formation of the overlying stitches *b*. Inasmuch as the follower 465 is in the middle of one of the active groove portions 705 of the needle-vibration cam 467 when the latter is in its home or rest position, it follows that the needle is shifted only through one-half of its amplitude of vibration during the first intermittent forward feed of the needle and shuttle for the formation of the first overlying stitch *b2* (Fig. 1). Furthermore, due to the speed ratio of 4 to 1 between the needle crank 66 (Fig. 2) and the feed cam 316, the needle and shuttle are intermittently fed on each second reciprocation of the needle only, resulting in the disposition of each second overlying stitch *b* at right angles to the longitudinal axis of the tack (Fig. 1). During this indexing of the cam shaft 555, one of the depressions 704 in the otherwise concentric periphery of the cam disc 610 (Fig. 25) has also been advanced so that the follower 529 comes to rest in the middle of said depression, resulting in withdrawal of the pawl 505 from the position 505a in Fig. 33 into the position 505b in Fig. 34, preparatory for a thread severing and 30 clamping operation.

50 During the last intermittent forward feed of the needle in the formation of the overlying stitches *b*, the finger 641 again trips the rocker 637, bringing thereby the cam 625 into alinement with the plunger 618 for the next indexing of the cam shaft 555 by the cam lobe 660 while the needle moves through a portion of its upstroke from the last penetrated hole *b24* in the work *W* (Fig. 1). During this next indexing of the cam shaft 555, the lobe 700 of the cam disc 558 moves away from the follower portion 559 of the rocker 560 to cause disengagement of the needle-vibration clutch 472 just when the follower 465 has arrived midway of one of the active groove portions 705 of the needle-vibration cam 467. Also, the lobe 710 of the cam disc 570 has been advanced into cooperative engagement with the follower portion 571 of the rocker 572, resulting in disengagement of the sewing clutch 88, 98. Furthermore, the depression 704 of the cam disc 610 (Fig. 25) has also been advanced beyond the follower 529, resulting in an advance movement of the pawl 505 from the position 505b (Fig. 34) into the position 505a (Fig. 33) and, consequently, in a thread severing and clamping operation.

The needle and shuttle then return to home position. During this idle return feed of the needle and shuttle, the former is neither reciprocated nor vibrated, while the latter is not rotated, so that no stitches are formed. The return feed of the needle and shuttle elements is under the control of the feed cam 316 (for overlying stitches), i. e., these elements are returned to home position in steps which are equal to those for the formation of the overlying 10 stitches, not only as to their length but also as to their timed relation with the needle-crank motion. During the last idle return step of the needle and shuttle, the finger 640 again trips the rocker 637, thereby shifting the cam disc 624 15 preparatory for a ratchet indexing operation which will take place just when the needle and shuttle arrive in home position. During this last indexing of the cam shaft 555, all the cams thereon are returned into the position shown in Figs. 20 25 and 27 to 30, inclusive, with the result that the frame 320 (Fig. 12) is shifted to bring the feed cam 315 (for underlying stitches) into cooperative engagement with its follower 370, the driving member 358 of the reverse clutch 356 (Fig. 4) 25 is shifted into engagement with its driven member 352 for a forward feed, and the main clutch 88, 364 (Fig. 4) is disengaged.

Inasmuch as the ratchet 615 has 12 teeth and is indexed the angular distance of only 6 teeth 30 during a complete cycle of operation of the machine, because the formation of a tack requires 6 reversals of the feed cams and the indexing of the cam shaft takes place at each of said reversals, it stands to reason that the cam shaft 555 is rotated through 180 degrees during one complete cycle of operation of the machine. Hence, the various cams are so designed that they perform their designated operations during a semi-revolution of the cam shaft and repeat the same operations 40 during the following semi-revolution of the cam shaft.

Fig. 47 illustrates the timed relation between certain major portions of the machine performed during the formation of a tack such as that 45 shown in Fig. 1.

The approximate sinus curves *f* in column I represent needle reciprocations. It will be observed that the needle starts from a position one third below its uppermost position. 50

The inclined lines *g*' to *g10*, inclusive, in column II represent the two forward and two return feeds of the needle and shuttle during the formation of the four superimposed lines *a1* to *a4* of underlying stitches *a*. The inclined lines *h1* to *h12*, inclusive, represent the forward feed of the needle and shuttle during the formation of the overlying stitches *b*, while the inclined lines *h13* to *h24*, inclusive, represent the idle return of the needle and shuttle after the formation of the overlying stitches *b* into the home or starting position. The solid horizontal lines between all feed-representing lines *g* and *h* represent the time periods during which a lock stitch or stitches (two overlying stitches) will be formed. It will be observed that the full horizontal lines between consecutive feed-representing lines *h* are twice as long as those between the lines *g*, indicating that the needle and shuttle are indexed only after the formation of every second lock-stitch (Fig. 1). 70 The horizontal dotted lines between the lines *h13* to *h24* merely indicate the time lapse between successive feeding steps of the needle and looper during the idle return of the same into home position while no stitches are formed.

The inclined lines *i1* to *i16*, inclusive, in column III represent the vibrations of the needle during the formation of the overlying stitches *b*. It will be observed that the needle is vibrated only 5 through one-half of its normal amplitude at the beginning and end of the formation of the overlying stitches.

The vertical lines *k1* to *k6* in column IV represent the 6 reversals of the feed cams 315 and 316 10 during one cycle of operation of the machine.

The vertical *j1* and *j2* in column V represent the alternate engagement of the feed cams 315 and 316 with their respective followers 370 and 372 during one cycle of operation of the 15 machine.

The vertical lines *m1* and *m2* in column VI represent the engagement and disengagement, respectively, of the sewing clutch 88, 98 during one cycle of operation of the machine.

20 The vertical lines *n1* and *n2* in column VII represent the engagement and disengagement, respectively, of the main clutch 88, 96 during one cycle of operation of the machine.

The vertical line *o* in column VIII finally 25 represents the thread severing and clamping operation during one cycle of operation of the machine.

For a better understanding of the coordination of the feed cams 315 and 316 with the uniformly 30 rotating needle-crank 66, reference is had to Figs. 38 to 46, inclusive. These figures illustrate prominent angular positions of the needle-crank element 66 and the corresponding angular positions of the rises 374 and 378 of the feed cam elements 315 and 316, respectively.

Fig. 38 shows the elements in home position. It can be understood from this figure that the needle is one third of its stroke below its uppermost position, while the rises 374a and 378a of 40 the feed cams 315 and 316 assume positions in which they are about to cooperate with the followers 370 and 372, respectively, if in engagement with the latter. As earlier explained, the feed cam 315 is in operative engagement with its follower 370 and the reverse clutch 558 is conditioned for forward feed, when the machine is at rest. Assuming, therefore, that the needle crank 66 rotates clockwise as viewed in Figs. 38 to 46, inclusive, and that the feed cam 315 rotates also 45 clockwise as viewed in Figs. 38 to 41, inclusive, when the machine is started, it follows that the rise 374a will immediately feed the needle and shuttle in the direction of the arrow 550 (Fig. 1) a complete distance *c*, while the needle rises in 50 the meantime from home position into the uppermost dot-and-dash line position 53a, Fig. 1. This is accomplished by extending each rise 374 of the feed cam 315 over 30 degrees of the periphery of the latter. The needle then reaches its 55 uppermost position just when the rise 374 has passed the follower 370 (Fig. 39), due to the fact that the speed ration between the needle crank 66 and the feed cam 315 is two to one. Inasmuch as the rises 374 of the feed cam 315 are 60 diametrically opposite each other, it is also clear that the rises 374 perform their forward feeding function every time the needle passes through the last third of its upstroke, resulting in the formation of the underlying stitches *a* of the first 65 line *a1*.

During the last intermittent forward feed of the needle and shuttle (Fig. 40) from the stitch *a5* to the stitch *a6* (Fig. 1), the cam 624 (Figs. 4 and 25) is shifted so as to bring one of the cam lobes 660, 661 of said cam into cooperative align-

ment with the plunger 618. Such shifting of the cam 624 takes place while the cam lobes 660, 661 move from the dotted line position to the full line position in Fig. 40 during this last forward feed of the needle and shuttle which is shown just completed in Fig. 40. Assuming that the plunger is disposed at the same place where the follower 370 is indicated, it is then clear that the shifting of the cam 624 takes place when no cam lobe 660 or 661 can possibly knock the plunger 618 down to index the ratchet 615. The knock-down of the plunger 618 and the corresponding indexing of the ratchet 615 and cam shaft 555 takes place after the needle completes the last underlying stitch *a6* in the line *a1*, as is evidenced by the progress of the cam lobes 660, 661 and the needle crank 66 from the position in Fig. 40 over the position in Fig. 41 and into the position in Fig. 42. In the latter position, the cam lobes 660, 661 have completed their knockdown function, with the result that the feed cam 315 is already reversed before the next forward feed by the rise 374b (Fig. 42) could take place.

The first return feed of the needle and shuttle is delayed until the feed cam 315 has rotated 150 degrees in the opposite direction when the other rise 374c (Fig. 45) starts to perform its return feed function. During this idle reverse rotation of the feed cam 315 through 150 degrees, the needle crank has passed through 300 degrees from the position shown in Fig. 42 into the position shown in Fig. 45, with the result that the needle passes twice through the same hole and forms two stitches *a6* before the same is fed rearwardly for the first time for the formation of the second line *a2* of underlying stitches. It also appears from Fig. 45 that the needle and shuttle are fed rearwardly while the needle crank 66 advances from the full line position into the dotted line position shown in Fig. 45, i. e., while the needle passes through the second third of its upstroke. Obviously, the following intermittent return-feed steps during the formation of the second line *a2* of underlying stitches take place every time the needle crank 66 travels through the angular range shown in Fig. 45.

Figs. 43 and 44 illustrate the momentary angular positions of the rises 374 of the feed cam 315 during the return feed when the needle crank 66 assumes the positions illustrated in these figures.

During the last intermittent return-feed of the needle from the stitch *a1* (Fig. 1) to home position (see also Figs. 45 and 46), the cam 624 is shifted so that one of its cam lobes 660, 661 knocks the plunger 618 down while the cam lobe 55 is moving into alignment with said plunger. Hence, when the needle crank 66 arrives in the position shown in Fig. 46, the rise 374c has just completed the last intermittent return-feed of the needle, and the feed cam 315 is at this very instant reversed as evidenced by the position of the cam lobes 660, 661 in Fig. 46 in which the indexing of the cam shaft 555 has been completed. At the very moment of the reversal of the feed cam 315, the needle assumes, therefore, the full line position shown in Fig. 1, i. e., home position, having thereby risen to this position in the manner indicated by the dot-and-dash lines 800 and 801.

On reversal of the feed cam 315, its rise 374c causes an immediate forward-feed step of the needle and shuttle for the formation of the first underlying stitch *a9* of the line *a3*, while the needle crank 66 has in the meantime been advanced from the position shown in Fig. 46 or 38

into the position shown in Fig. 39. Hence, the following intermittent forward feeds of the needle for the formation of the line *a*3 of underlying stitches take place every time when the needle 5 passes through the last third of its upstroke. Conversely, the following return-feed steps of the needle for the formation of the last line *a*4 of underlying stitches take place every time when the needle passes through the second third of its 10 upstroke.

It can now be understood that the intermittent forward-feeds of the needle for the formation of both lines *a*1 and *a*3 of underlying stitches take place while the needle crank 66 passes through 15 an angular region which is 60 degrees displaced from the angular region through which the needle travels while the intermittent return-feeds of the needle for the formation of both lines *a*2 and *a*4 of underlying stitches take place.

20 On return of the needle into home position after the formation of the last underlying stitch *a*10 of the line *a*4, the feed cams 315 and 316, which always rotate in the same directions, are reversed, and the feed cam 316 is brought into 25 cooperative engagement with its follower 372, causing an immediate forward-feed step of the needle (Fig. 38) through the distance *d* (Fig. 1), while the needle is simultaneously vibrated in order to position the same for the first overlying 30 stitch *b*2. The speed ratio between the feed cam 316 and the needle crank 66 is 4 to 1 which is observed in Figs. 38 to 46, inclusive.

Each forward-feed step of the needle during the formation of the overlying stitches *b* takes 35 place while the needle moves through the last third of its upstroke on each second reciprocation as is evidenced by the fact that the rise 378a of the feed cam 316 is ready to cooperate with its follower 372 when the needle crank 66 assumes the momentary position shown in Fig. 42.

40 On reversal of the forward feed of the needle, the rise 378a of the feed cam 316 stops just as the same would cooperate with the follower 372 (Fig. 42), with the result that the needle is not immediately fed backward into home position, 45 but remains in alignment with the last overlying stitch *b*24 for the duration of 33 $\frac{1}{2}$ degrees rotation of the needle crank 66 (Figs. 42 and 45). This would result in the passage of the needle twice through the same hole at *b*24, were it not 50 for the fact that the sewing clutch 88, 98, has been disengaged after the first reciprocation through this hole.

It will also be observed from Figs. 38 to 42, inclusive, that the needle crank 66 makes two complete revolutions to each intermittent feed of the needle under the control of the feed cam 316, resulting in the disposition of each second overlying stitch *b* at right angles to the longitudinal axis of the tack. Also, the forward feed of the needle for the formation of the over-lying stitches *b* takes place while the needle crank travels through the same angular range as during the forward feed of the needle for the formation of the underlying stitches, as can be observed from Figs. 38, 39 and 42. Likewise, the return feed of the needle after the formation of the over-lying stitches takes place while the needle travels through the same angular range as during the return feed of the needle for the formation of the underlying stitches. This is evidenced by the fact that the needle, when in alignment with the stitch hole *b*24 (Fig. 1) and after reversal of the feed cam 316 in the position shown in Fig. 42, does not start on its return feed until the rise 378b

of the cam 316 has traveled through 165 degrees from the position shown in Fig. 43 into the position shown in Fig. 45. In the latter cam position, the needle crank assumes the full line position in Fig. 45, indicating that the return feed of the needle into home position will take place every time when the needle passes through the second third of its upstroke on each second reciprocation.

The cam shaft 555 will be indexed during the 10 last intermittent return feed of the needle (Fig. 46), thereby restoring the feed cams 315 and 316 as well as the needle crank 66 to initial starting position (Fig. 38) just as the main clutch 88, 96, is automatically disengaged.

15 While the needle in home position is shown and described as being one third of its stroke below its uppermost position, it is preferable to select the uppermost position of the needle as the home position. In that case, the needle crank is merely displaced 60 degrees from the home position shown in Fig. 38 and brought into the dot-and-dash line position 66a (Figs. 38 and 46) without changing the angular positions of the feed cams 315 and 316, nor the illustrated angular positions 20 of the cam lobes 660, 661 of the cam 624. In other words, the coordination of the feed cams 315 and 316 and of the cam lobes 660, 661 is not at all disturbed, while the needle crank is merely displaced 60 degrees. In doing so, the needle 25 passes through the first third of its downstroke and through the last third of its upstroke during the intermittent forward and return feeds, respectively, of said needle, as can be readily understood. The selection of the vertical disposition 30 of the needle in home position is entirely a matter of choice, so long as the intermittent feeds of the needle take place in either direction while the same is withdrawn from the work.

35 Before explaining the adjustment of certain elements of the machine for varying the size of the tack and/or the number of overlying stitches and/or underlying stitches, reference is had to Figs. 3 and 22. These figures show that the rotation of the fingers 640 and 641 in either direction is always a step by step motion derived from either feed cam 315 or 316, because the lever 425 is rocked by either feed cam and the gear segment 658 of said lever is in permanent driving connection, through the gears 657 and 656, shaft 557 and gear 655, with the gear portion 653 of the sleeve 642 (Fig. 11) which provides the finger 640 and is locked with the sleeve 643 that provides the other finger 641. It can, therefore, be understood that the angle between the fingers 640 and 641 varies with the number of underlying or overlying stitches. However, the variation of the angle between these fingers is not proportional to a variation of the number of overlying or underlying stitches for reasons to be explained presently.

40 When the feed cam 316 (for overlying stitches) is cooperating with its follower 372, consecutive intermittent rocking motions of the lever 425 are of different amplitude because the linear motion of the follower 372 and, consequently, of the rectangular block 423 is transformed into a rocking motion of the lever 425 about its fixed pivot axis 430. Consequently, random angular adjustment of the sleeve 643 with its arm 641, for a variation of the number of overlying stitches, would most probably result in a condition in which said finger would not completely shift the pin 639 from the normal dotted line position to the dot-and-dash line position 639b in Fig. 22

during all supposedly last intermittent forward feeds of the needle. The result would be that the disc 624 is only partially shifted and that one of its cam lobes 660 or 661, which is supposed to cause an indexing of the ratchet 615 and cam shaft 555 at this time and, hence, a reversal of the feed cams, will not knock the plunger 618 down for a ratchet indexing operation. The needle would, therefore, be fed forwardly another 10 step, whereby the finger 641 would overtravel its designated end position and the cam disc 624 would likewise overtravel its designated position for a ratchet-indexing operation. The final result would be that the machine would be out 15 of time before the completion of the first tack, as can be readily understood.

To prevent such an occurrence, the serrations 648 in the index disc 647 are harmonically spaced from each other and stitch numbers indicated 20 (Fig. 24) at intervals of 5 in order to enable the operator of the machine to register the proper serration, corresponding to the desired number of overlying stitches, with the rib 649 of the counter disc 650. Only then does the finger 25 641 trip the pin 639 into the invariable dot-and-dash line position 639b (Fig. 22), regardless of the number of stitches to which the index disc 647 has been adjusted. Only then does the machine remain in time and produce a tack of the 30 type disclosed in Fig. 1, regardless of the number of overlying stitches. In other words, the coordination of the elements 66, 315 and 316 as shown in Figs. 38 to 46, inclusive, is then never disturbed regardless of the number of overlying 35 stitches.

Fig. 22 shows, for instance, a possible maximum amplitude of $36^\circ 52'$ of the rocking lever 425, corresponding to a maximum adjustment of the finger 641 through $147^\circ 28'$, this angle being 40 derived at by reason of the fact that the speed ratio between the gear segment 658 and the gear 653 is 1 to 4. This maximum amplitude of $36^\circ 52'$ of the lever 425 is, for instance, capable of producing a maximum number of 39 overlying 45 stitches, as also indicated on the index disc 647 (Fig. 24). For instance, if 25 overlying stitches are desired, the index disc 647 is manipulated and the serration corresponding to the indication "25" (Fig. 24) brought into registry with 50 the rib 649 of the counter disc 650. The arm 641 is thereby rotated into the dot-and-dash line position 641a (Fig. 22) which is 44 degrees from its one extreme position of adjustment shown in full lines, while the lever 425 rocks within the 55 range between its invariable full-line home position and the dot-and-dash line position 425a.

The above data are, of course, given only by way of example, because other angles, speed ratios and maximum numbers of overlying stitches 60 may be selected at will.

If it is desired to vary the length of the tack, the following course is advisable. Having the index disc 647 adjusted for the desired number of overlying stitches so that the lever 425 rocks 65 through a certain angular distance, the rack 428 (Figs. 3 and 12) is shifted in its guideways 421 until the rectangular block 443 is so spaced from the pivot axis 451 of the lever 425 that the desired overall length of the tack, i. e., overall 70 length of the overlying stitches, is obtained when said lever travels through its rocking range. Thereafter, the rack 397 (Figs. 3 and 21) is shifted in its guideways 396 until the foremost of a number of underlying stitches in each line a_1 to 75 a_4 coincide in their position with the adjacent

end of the overlying stitches as shown in Fig. 1. The first adjustment may, for instance, result in the formation of a certain number of underlying stitches, the foremost of which are spaced in either direction longitudinally of the tack 5 from the adjacent end of the overlying stitches. A subsequent adjustment or adjustments will, however, bring about the above-mentioned desired condition.

I claim:

1. In a sewing machine, the combination of a work-holding device; a stitch-forming device; and adjustable mechanism for causing between said devices relative movements tracing the underlying and overlying stitch groups of a tack 15 of which the over-all length of one group is variable independently of the over-all length of the other group.

2. In a sewing machine, the combination of a work-holding device; a stitch-forming device; 20 and adjustable mechanism for causing between said devices relative movements tracing the underlying and overlying stitch groups of independently variable over-all lengths of a tack.

3. In a sewing machine, the combination of a work-holding device; a stitch-forming device; adjustable mechanism for causing between said devices relative movements tracing the underlying and overlying stitch groups of a tack of which the over-all length of one group is variable 30 independently of the over-all length of the other group; and means for operating the stitch-forming device in timed relation with the mechanism, said mechanism being also adjustable to vary the number of stitches in said one group. 35

4. In a sewing machine, the combination of a work-holding device; a stitch-forming device; mechanism for causing between said devices relative movements tracing the underlying and overlying stitch groups of a tack; and means for operating the stitch-forming device in timed relation with the mechanism, said mechanism being 40 adjustable to independently vary the over-all length of either stitch group as well as the number of stitches in either group. 45

5. In a sewing machine, the combination of a work-holding device; a stitch-forming device; mechanism for causing between said devices relative movements tracing the underlying and overlying stitch groups of a tack; and means for operating the stitch-forming device in timed relation with the mechanism, said mechanism being 50 adjustable to vary the width of the overlying stitch group and the over-all length of one group independently of the over-all length of the other 55 group.

6. In a sewing machine, the combination of a work-holding device; a stitch-forming device; adjustable mechanism for causing between said devices relative movements tracing the underlying and overlying stitch groups of a tack of variable width of which the underlying group consists of at least one linear row of several stitches; and means for operating the stitch-forming device in timed relation with the mechanism, said 60 mechanism being also adjustable to vary the length of consecutive underlying stitches in said row.

7. In a sewing machine, the combination of a work-holding device; a stitch-forming device; 70 adjustable mechanism for causing between said devices relative movements tracing the underlying and overlying stitch groups of a tack of variable width of which the over-all length of one of said stitch groups is variable independent- 75

- entity of the over-all length of the other stitch group; and means for operating the stitch-forming device in timed relation with the mechanism, said mechanism being also adjustable to vary 5 the number of underlying stitches.
8. In a sewing machine, the combination of a work-holding device; a stitch-forming device; adjustable mechanism for causing between said devices relative movements tracing the underlying 10 and overlying stitch groups of independently variable over-all lengths and independently variable number of stitches of a tack of variable width; and means for operating the stitch-forming device in timed relation with said mechanism.
9. In a sewing machine, the combination of a stationary work holder; a stitch-forming device; means for operating said device; and mechanism for moving said device so as to position the underlying and overlying stitches of a tack in the stationary work.
10. In a sewing machine, the combination of a stationary work holder; a stitch-forming device; means for operating said device; and adjustable 15 mechanism for moving said device so as to position the underlying and overlying stitches of a tack of variable width in the stationary work.
11. In a sewing machine, the combination of a stationary work holder; a stitch-forming device; means for operating said device; and adjustable 20 mechanism for moving said device so as to position the underlying and overlying stitches of a tack of variable over-all length in the stationary work.
12. In a sewing machine, the combination of a stationary work holder; a stitch-forming device; means for operating said device; and adjustable 25 mechanism for moving said device so as to position the underlying and overlying stitch groups of different over-all lengths of a tack in the stationary work.
13. In a sewing machine, the combination of a stationary work holder; a stitch-forming device; means for operating said device; and adjustable mechanism for moving said device so as to position the underlying and overlying stitch groups of independently variable over-all lengths of a tack in the stationary work.
14. In a sewing machine, the combination of a stationary work holder; a stitch-forming device; means for operating said device; and adjustable mechanism for moving said device so as to position in the stationary work the underlying and overlying stitches of a tack having a variable 40 number of overlying stitches.
15. In a sewing machine, the combination of a stationary work holder; a stitch-forming device; means for operating said device; and adjustable mechanism for moving said device so as to position in the stationary work the underlying and overlying stitches of a tack in which the distance between the overlying stitches longitudinally of the tack is variable.
16. In a sewing machine, the combination of a reciprocable needle; a stationary work holder; and means for laterally moving the needle so that the same traces the underlying and overlying stitches of a tack in the stationary work.
17. In a sewing machine, the combination of a stationary work holder; a reciprocable needle 50 bar; and means for laterally moving the needle so that the same traces the underlying and overlying stitches of a tack in the stationary work and is permanently disposed in a plane at right angles to the work and to the longitudinal axis of the tack.
18. In a sewing machine, the combination of a needle bar; a rotatable and axially slidable member supporting said bar for longitudinal reciprocation transversely to the axis of rotation of said member; means for axially sliding said member; and other means for rocking said member. 5
19. In a sewing machine, the combination of a support; a member rotatable and axially movable in said support; a needle bar supported by said member for longitudinal reciprocation transversely to the axis of rotation of the latter; and means for rocking said member in any position. 10
20. In a sewing machine, the combination of a support; a member rotatable and axially movable in said support; a needle bar supported by said member for longitudinal reciprocation transversely to the axis of rotation of the latter; means for rocking said member in any position; and means carried by said member for reciprocating the needle bar. 15
21. In a sewing machine, the combination of a needle bar; a support; a carrier having a shank rotatable and axially slidable in said support and itself supporting said bar for longitudinal reciprocation transversely to the axis of rotation of said carrier, said shank being also provided with longitudinally spaced peripheral gear teeth extending at right angles to said axis; a rotatable gear in permanent mesh with said gear teeth; and means for rocking said member in any position. 20
22. In a sewing machine, the combination of a needle bar; a support; a carrier having a hollow shank rotatable and axially slidable in said support and itself supporting said bar for longitudinal reciprocation transversely to the axis of rotation of said carrier; means for reciprocating said bar, said means including a driven shaft journaled in said hollow shank and axially moving with the same, an axially immovable drive shaft extending coaxially of said driven shaft, and a spline connection between said shafts. 25
23. In a sewing machine, the combination of a needle bar; a rotatable and axially movable carrier supporting said bar for longitudinal reciprocation transversely to the carrier axis; two members rotatable about the same axis parallel to said carrier axis, one of said members being axially immovable and the other member being axially movable together with said carrier and permanently coupled to said one member; means for rocking said one member; and a link connecting said other member and carrier at eccentric points thereof. 30
24. The combination in a sewing machine as set forth in claim 23, in which said other member is provided with an arcuate groove wherein its pivot connection with the link is adjustable, said groove being concentric about the pivot connection between the link and carrier when the needle bar is in home position. 35
25. The combination in a sewing machine as set forth in claim 23, in which said other member is provided with an arcuate groove wherein its pivot connection with the link is adjustable, said groove extending through the axis of rotation of said other member and being concentric about the pivot connection between the link and carrier when the needle bar is in home position. 40
26. In a sewing machine, the combination of a non-rotatable but axially movable hollow carrier having axially spaced rack teeth in its outer circumference; a thread-handling element; a device carrying said element and being supported in said carrier for rotation about an axis par- 70
- 75

allel to the carrier axis; an axially immovable drive shaft extending coaxially of the device and into said hollow carrier and being splined to said device; and a rotary gear in mesh with said rack teeth.

27. In a sewing machine, the combination of a work-holding device; a stitch-forming device; and means including two followers and two therewith alternately engageable rotary feed cams for causing intermittent relative linear movements of different length, respectively, between said devices in opposite directions, respectively, on rotation of said cams, respectively, in opposite directions.

15 28. The combination, in a sewing machine as set forth in claim 27, in which each cam has a peripheral cam groove consisting of axially spaced, part-annular groove portions which are joined by offset groove portions, the part-annular groove portions being differently axially spaced in said cams, respectively.

25 29. The combination in a sewing machine as set forth in claim 27, further including a pivoted frame on which said cams are rotatably mounted on opposite sides of the pivot axis so as to be alternately rockable into engagement with their respective followers.

30. The combination in a sewing machine as set forth in claim 27, further including a pivoted frame on which said cams are rotatably mounted on opposite sides of the pivot axis so as to be alternately rockable into engagement with their respective followers, a drive gear loosely mounted on said pivot, and gears rotatable with said cams and in permanent mesh with said drive gear.

31. The combination in a sewing machine as set forth in claim 27, further including a pivoted frame on which said cams are rotatably mounted on opposite sides of the pivot axis so as to be alternately rockable into engagement with their respective followers, a first gear loosely mounted on said pivot, gears rotatable with said cams and in permanent mesh with said drive gear, a first bevel gear rotatable with said drive gear, a drive shaft, two driven clutch elements freely rotatable but axially immovable on said drive shaft, said elements being provided with bevel gears meshing with diametrically opposite portions of said first bevel gear, and a driving clutch element splined on said drive shaft between the driven clutch elements and slidable into engagement with either driven element.

32. In a sewing machine, the combination of a work-holding device; a stitch-forming device; a longitudinally movable rack having a transverse slot; a slotted lever pivotally mounted for rotation in a plane parallel to the rack and having a first pin projecting into the rack slot; a follower movable parallel to the rack and having a pin projecting into the lever slot; a feed cam cooperable with said follower for causing intermittent movements of the rack in either direction depending on the direction of rotation of said cam; and means translating the intermittent rack movements in both directions into intermittent relative linear movements of corresponding length and in corresponding directions between said devices.

33. The combination in a sewing machine as set forth in claim 32, in which said first pin is adjustable in the rack slot toward and away from the pivot axis of said lever to thereby vary the length of the intermittent rack movements.

34. The combination in a sewing machine as set forth in claim 32, further including an angu-

larly adjustable pinion coaxially of the pivot axis of said lever, and a rack element providing said first pin and being slidable in a guideway of said lever and in mesh with said pinion, whereby the length of the intermittent rack movements is varied on angular adjustment of said pinion.

35. In a sewing machine, the combination of a work-holding device; a stitch-forming device; a longitudinally movable rack having two transverse slots; two slotted levers pivotally mounted for rotation in planes parallel to the rack and having pins projecting into the slots, respectively, of the rack; two followers movable parallel to the rack and having pins projecting into the slots of said levers, respectively; two rotary feed cams alternately engageable with the followers, respectively, for causing intermittent movements of different length, respectively, of the rack in opposite directions, respectively, on rotation of said cams, respectively, in opposite directions; and means translating the intermittent movements of the rack in both directions into intermittent relative linear movements of corresponding length and in corresponding directions between said devices.

36. The combination in a sewing machine as set forth in claim 35, in which the pins of said levers are independently adjustable toward and away from the pivot axes of their respective levers to thereby vary the length of the intermittent rack movements as caused by either cam.

37. In a sewing machine, the combination of a work-holding device; a stitch-forming device; means including a rotary feed cam for causing intermittent relative linear movements between said devices in either direction depending on the direction of rotation of said cam; a reversible drive for said cam; means including another cam for reversing said drive; and mechanism indexing said other cam after a predetermined number of said intermittent relative movements in either direction, said other cam being so designed as to cause reversal of said drive during each indexing step.

38. The combination in a sewing machine as set forth in claim 37, in which said mechanism is adjustable to index said other cam after a variable number of said intermittent relative movements in either direction.

39. The combination in a sewing machine as set forth in claim 37, in which said mechanism includes a pivoted member normally yieldingly urged into inoperative position and causing reversal of the drive on becoming rocked in either direction therefrom, and angularly spaced fingers together intermittently rotated in timed relation with, and in directions corresponding to, said intermittent relative movements, said fingers rocking said member during the last of a predetermined number of their intermittent rotations in either direction.

40. The combination in a sewing machine as set forth in claim 37, in which said mechanism includes a pivoted member normally yieldingly urged into inoperative position and causing reversal of the drive on becoming rocked in either direction therefrom, and angularly spaced fingers together intermittently rotated in timed relation with, and in directions corresponding to, said intermittent relative movements, one of said fingers being angularly adjustable relative to the other finger so that said fingers rock said member during the last of a variable number of their intermittent rotations in either direction, where-

by the number of said relative movements in each direction may be varied.

41. The combination in a sewing machine as set forth in claim 37, in which said mechanism includes a ratchet rotatable with said other cam, an indexing pawl therefor, an axially movable pawl-operating cam rotated by the drive and having two axially spaced camming surfaces and being normally yieldingly held axially in a position in which said surfaces are out of cooperative alignment with said pawl, a pivoted member so connected with said pawl-operating cam that the latter is axially shifted to bring either camming surface into cooperative alignment with the pawl depending on the direction in which said member is rocked, and angularly spaced fingers together intermittently rotated in timed relation with, and in directions corresponding to, said intermittent relative movements, said fingers rocking said member during the last of a predetermined number of their intermittent rotations in either direction.

42. In a sewing machine, the combination of a work-holding device; a stitch-forming device; means including two followers and two therewith alternately engageable feed cams for causing intermittent relative linear movements of different length, respectively, between said devices in opposite directions, respectively, on rotation of said cams, respectively in opposite directions; a single reversible drive for both cams; means including another cam for reversing said drive; and mechanism indexing said other cam after different predetermined numbers, respectively, of said intermittent relative movements in either direction as caused by said feed cams, respectively, said other cam being so designed as to cause reversal of said drive during each indexing step.

43. The combination in a sewing machine as set forth in claim 42, in which said mechanism is adjustable to index said other cam after a variable number of said intermittent relative movements in either direction as caused by one feed cam without varying the number of said intermittent relative movements in either direction as caused by the other feed cam.

44. The combination in a sewing machine as set forth in claim 42, in which said mechanism is adjustable to index said other cam after independently variable numbers, respectively, of said intermittent relative movements in either direction as caused by said feed cams, respectively.

45. In a sewing machine, the combination of a work-holding device; a stitch-forming device; a longitudinally movable rack having a transverse slot; a slotted lever pivotally mounted for rotation in a plane parallel to the rack and having a first pin projecting into the rack slot; a follower movable parallel to the rack and having a pin projecting into the lever slot; a feed cam rotatable about an axis parallel to the rack and cooperating with said follower for causing intermittent movements of said rack in either direction depending on the direction of rotation of the cam, said cam having equally axially spaced part annular cam groove portions joined by axially aligned offset cam groove portions; means translating the intermittent movements of said rack in both directions into intermittent relative linear movements of corresponding length and in corresponding directions between said devices; a reversible drive for said cam; mechanism for reversing said drive and including a pivoted member normally yieldingly urged into inoperative position and causing reversal of said drive on becoming rocked in either direction therefrom; angularly spaced fingers mounted for combined rotation about the same axis; and gear means transmitting the intermittent rotations in either direction of one of said levers to the fingers, whereby said fingers rock said member during the last of two different numbers, respectively, of intermittent rack movements in either direction as caused by said cams, respectively.

member normally yieldingly urged into inoperative position and causing reversal of said drive on becoming rocked in either direction therefrom; angularly spaced fingers mounted for combined rotation about the same axis; and gear means transmitting the intermittent rotations of said lever in either direction to the fingers, said fingers rocking said member during the last of a predetermined number of their intermittent rotations in either direction.

46. The combination in a sewing machine as set forth in claim 45, in which said first pin is adjustable in the rack slot toward and away from the pivot axis of said lever to thereby vary the length of the intermittent rack movements, and one of said fingers is connected with said gear means while the other finger is angularly adjustable to thereby vary the number of said intermittent rack movements in either direction.

47. The combination in a sewing machine as set forth in claim 45, further including two concentrically rotatable members carrying said fingers, respectively, and having concentric serrations and a therewith interlockable tooth, respectively, one of said members being connected with said gear means and the other member being angularly adjustable to thereby vary the number of intermittent rack movements in either direction.

48. The combination in a sewing machine as set forth in claim 45, further including two concentrically rotatable members carrying said fingers, respectively, and having concentric serrations and a therewith interlockable tooth, respectively, one of said members being connected with said gear means and the other member being angularly adjustable to thereby vary the number of intermittent rack movements in either direction, and said serrations being harmonically spaced so as to reverse the feed cam always in the same angular position relative to the follower regardless of the number of intermittent rack movements in either direction.

49. In a sewing machine, the combination of a work-holding device; a stitch-forming device; a longitudinally movable rack having two transverse slots; two slotted levers pivotally mounted for rotation in planes parallel to the rack and having pins projecting into the slots, respectively, of the rack; two followers movable parallel to the rack and having pins projecting into the slots of said levers, respectively; two rotary feed cams alternately engageable with said followers, respectively, for causing intermittent movements of different length, respectively, of said rack in opposite directions, respectively, on rotation of said cams, respectively, in opposite directions; means translating the intermittent movements of said rack in both directions into intermittent relative linear movements of corresponding length and in corresponding directions between said devices; a single reversible drive for both cams; mechanism for reversing said drive and including a pivoted member normally yieldingly urged into inoperative position and causing reversal of said drive on becoming rocked in either direction therefrom; angularly spaced fingers mounted for combined rotation about the same axis; and gear means transmitting the intermittent rotations in either direction of one of said levers to the fingers, whereby said fingers rock said member during the last of two different numbers, respectively, of intermittent rack movements in either direction as caused by said cams, respectively.

50. The combination in a sewing machine as set forth in claim 49, in which the pin of one of said levers is adjustable in its respective rack slot toward and away from the pivot axis of said one lever to thereby vary the length of the intermittent rack movements as caused by one of the feed cams. 5
51. The combination in a sewing machine as set forth in claim 49, in which the pins of said levers are adjustable in their respective rack slots toward and away from the pivot axes of said levers to thereby vary the length of the intermittent rack movements as caused by either feed cam. 10
52. The combination in a sewing machine as set forth in claim 49, in which one of said fingers is connected with said gear means and the other finger is angularly adjustable to thereby vary the number of intermittent rack movements in either direction as caused by only one feed cam or by both feed cams. 15
53. The combination in a sewing machine as set forth in claim 49, in which the pin of one of said levers is adjustable in its respective rack slot toward and away from the pivot axis of said one lever to thereby vary the length of the intermittent rack movements as caused by one of the feed cams, and one of said fingers is connected with said gear means while the other finger is angularly adjustable to thereby vary the number of intermittent rack movements in either direction as caused by only one feed cam or by both feed cams. 20
54. The combination in a sewing machine as set forth in claim 49, in which the pins of said levers are adjustable in their respective rack slots toward and away from the pivot axes of said levers to thereby vary the length of the intermittent rack movements as caused by either feed cam, and one of said fingers is connected with said gear means while the other finger is angularly adjustable to thereby vary the number of intermittent rack movements in either direction as caused by only one feed cam or by both feed cams. 25
55. In a sewing machine, the combination of a work-holding device; a stitch-forming device; means including two rotary feed cams for causing intermittent relative linear movement of different length, respectively, between said devices in opposite directions, respectively, on rotation of said cams, respectively, in opposite directions; mechanism operative on completed rotation of one of said cams through its preassigned working cycle for rendering the other cam operative during its preassigned working cycle; means reversing each operative cam on completed rotation through each of several preassigned parts of its working cycle; and means operable while the machine is at rest for rendering said one cam operative. 30
56. In a sewing machine, the combination of a work-holding device; a stitch-forming device; means including two followers and two therewith alternately engageable rotary feed cams for causing intermittent relative linear movements of different length, respectively, between said devices in opposite directions, respectively, on rotation of said cams, respectively, in opposite directions; a prime mover; a driving connection between said prime mover and said cams and including a reversible clutch and a manually engageable main clutch; mechanism operative on completion of a preassigned working cycle of one of said cams for engaging the other cam with its follower; means reversing said reversible clutch on completed rotation of each operative cam through each of several preassigned parts of its working cycle; and means disengaging said main clutch and reengaging said one cam with its follower on completion of the working cycle of said other cam. 35
57. In a sewing machine, the combination of a work-holding device; a stitch-forming device; means including two followers and two therewith alternately engageable feed cams for causing between said devices intermittent relative linear movements of different length, respectively and in opposite directions, respectively, on rotation of said cams, respectively, in opposite directions; a reversible drive for said feed cams; a first mechanism for reversing said drive; a second mechanism for alternately engaging said feed cams with their respective followers; a cam shaft; cam elements thereon for operating said mechanisms, respectively; and means indexing said cam shaft after predetermined numbers, respectively, of said intermittent relative movements in either direction as caused by said feed cams, respectively, said cam elements being so coordinated as to operate said first mechanism during each indexing step of the cam shaft, and said second mechanism during two predetermined recurrent indexing steps of said cam shaft. 40
58. In a sewing machine, the combination of a work-holding device; a stitch-forming device; means including two followers and two therewith alternately engageable feed cams for causing between said devices intermittent relative linear movements of different length, respectively, and in opposite directions, respectively, on rotation of said cams, respectively, in opposite directions; a prime mover; a driving connection between said prime mover and cams, said connection including a reversible clutch and a manually engageable main clutch between the latter and the prime mover; a first mechanism for reversing the reversible clutch; a second mechanism for alternately engaging said feed cams with their respective followers; a third mechanism for disengaging the main clutch; a cam shaft; cam elements thereon for operating said mechanisms, respectively; and means indexing the cam shaft after predetermined numbers, respectively, of said intermittent relative movements in either direction as caused by said feed cams, respectively, said cam elements being so coordinated as to operate said first mechanism during each indexing step of the cam shaft, said third mechanism during the last of a predetermined number of said indexing steps, and said second mechanism during an intermediate and said last indexing step. 45
59. The combination in a sewing machine as set forth in claim 58, further providing operating means for the stitch-forming device, a driving connection between the driven element of the main clutch and said operating means and including a sewing clutch, manually operable means for simultaneously engaging said main clutch and said sewing clutch, another mechanism for disengaging the sewing clutch, and another cam element on the cam shaft for operating said other mechanism during a predetermined indexing step of said cam shaft. 50
60. The combination in a sewing machine as set forth in claim 58, further providing operating means for the stitch-forming device, a driving connection between the driven element of the main clutch and said operating means and including a sewing clutch, manually operable means for simultaneously engaging said main clutch 70
- 70

and said sewing clutch, a fourth mechanism for disengaging the sewing clutch, a third device for causing relative reciprocations between the other devices in timed relation with, and transversely of, intermittent relative linear movements as caused by one feed cam, a fifth mechanism for operating said third device, and other cam elements on the cam shaft for operating said fourth mechanism during a predetermined indexing step 10 of the cam shaft and for rendering said fifth mechanism active and inactive during said intermediate and the following indexing step, respectively, of said cam shaft.

61. The combination in a sewing machine as set forth in claim 58, further providing operating means for the stitch-forming device, a driving connection between the driven element of the main clutch and said operating means and including a sewing clutch, manually operable means 20 for simultaneously engaging said main clutch and said sewing clutch, a fourth mechanism for dis-

engaging the sewing clutch, a third device for causing relative reciprocations between the other devices in timed relation with, and transversely of, intermittent relative linear movements as caused by one feed cam, a fifth mechanism for operating said third device, a sixth thread-cutting mechanism, and other cam elements on the cam shaft for operating said fourth mechanism during a predetermined indexing step of the cam shaft and said sixth mechanism during the same 10 predetermined indexing step, and for rendering said fifth mechanism active and inactive during said intermediate and the following indexing step, respectively, of said cam shaft.

62. In a sewing machine, the combination of a 15 needle bar; a pivoted member slidable in the direction of its pivot axis and supporting said bar for longitudinal reciprocation transversely to said axis; and means whereby said member may be rocked and axially slid.

SAMUEL W. AVIS.
